UNITED STATES PATENT OFFICE.

DARIEN W. DODSON, OF HARTFORD, CONNECTICUT, ASSIGNOR TO THE AMERICAN TYPE-BAR MACHINE COMPANY, A CORPORATION OF WEST VIRGINIA.

MACHINE FOR FORMING CHARACTERS.

No. 911,957.

Specification of Letters Patent.

Patented Feb. 9, 1909.

Application filed July 24, 1896, Serial No. 600,378. Renewed July 9, 1903. Serial No. 164,922.

To all whom it may concern:

Be it known that I, DARIEN W. DODSON, a citizen of the United States, residing in Hartford, in the county of Hartford and 5 State of Connecticut, have invented certain new and useful Improvements in Machines for Forming Characters, of which the following is a specification.

This invention relates particularly to key-10 operated mechanisms, and more especially to machines adapted for forming, from suitable blanks, bars having, in the form illustrated, each a series of selected or composed types adapted for printing a corresponding series 15 or line of composed characters; although, as will be obvious, bars having various impression faces, other than type, can be produced in the same manner.

This invention is especially adapted and 20 intended as an improvement upon that shown, described, and claimed in my application Serial No. 600,151, filed July 22, 1896, in which I have illustrated a machine of the kind above referred to as provided with a 25 rotating turret, on which is mounted a slot-forming reducing-tool operative for reducing a longitudinal portion of the face of a blank, supported by a suitable blank-carrier in a position to permit the blank to be operated 30 upon when such slot-forming reducing-tool is in its operative position, to thus set off a portion of the blank at one side of the reduced portion; means—such as a suitable character-impressor or die—for forming the 35 desired character or impression face in the blank; and means for actuating these devices into and out of engagement with the blank. In said other application I have also shown a plurality of simultaneously-rotative carriers 40 supporting coöperative character-shaping tools, the operation being such that all of the carriers are simultaneously started, and, one after another, a tool of each carrier is caused to operate upon a segment of the blank.

45 One of the main features of the present invention is the provision of a plurality of independently - rotatable carriers, each of which carries a plurality of character or type shaping tools, and means for selectively 50 rotating a determined plurality of these carriers, to bring into working position a shaping tool of each of such carriers without bringing into operative position any of the tools supported by the other carriers of the 55 series; the object being to select any deter-

mined plurality of carriers, having operatively connected therewith the several character or type formative tools for an individual character, without regard to the orbital positions of the carriers or the orbital planes 60 in which the tools travel.

When several independently operable carriers are employed each having one or more type-shaping tools thereon, and especially when dies are employed disposed in sets on 65 different die-carriers, it will be seen that any one of these tools or dies on any carrier may be selected for use without bringing into action any one of the other die-carriers, and that so far as the dies are concerned any one 70 of the die-carriers supporting these dies may be brought into action or started without bringing into action or starting any other die-carrier. Hence it is possible, in a machine of this type, to mount a large number 75 of different dies in sets each set on a different carrier, with the carriers located in different positions, and yet any one of these carriers may be brought into operation at will to the exclusion of every other one, and any de- 80 sired die on the selected carrier may be brought to a working position without bringing to a working position any other die on that carrier; and the die-carriers and their dies, it should be noted, are operated in this 85 manner at all times without regard to the subsequent operation of the side-cutting tools and their carriers.

Another object of the invention is to furnish, in connection with feeding mechanism 90 for intermittently feeding a type-bar or other blank to bring successive segments thereof into position to be operated upon by the shaping-tools, a pair of oppositely-movable feed-controlling members operative into 95 engagement with each other positively to control the extent of the movements thereof, one of the feed members serving to actuate the feeding-mechanism and the other constituting a positive stop device for the former. 100

These and other novel features of the present invention, which will be hereinafter more particularly referred to, constitute instrumentalities for more perfectly carrying into effect the invention described in the application hereinbefore mentioned, the main object of which is therein described as the provision of means for setting off, or separating, successive segments or impression blanks on the edge or face of a bar or blank of proper 105 110

material, and for forming, or shaping, characters or impressions in the faces of the segments so set off from the body of the main blank or bar.

5 In the drawings accompanying this specification, Figure 1 is a plan of a machine, constructed in accordance with my present improvements. Fig. 2 is a detail plan of the blank-carrier, its feed-screw and auxiliary devices. Fig. 3 is a side elevation of the machine, with portions of the frame removed to show the construction more clearly. Fig. 4 is a detail transverse section of the turret-mechanism, (hereinafter described,) 10 the section being taken in line *a—a*, Fig. 5, looking in the direction of the arrow. Fig. 5 is a sectional front elevation of the machine, portions of the mechanism being removed more clearly to illustrate the operation of 15 the devices carried directly by the turret. Fig. 6 is an enlarged sectional, end elevation of the turret and the character or type shaping devices carried thereby, looking from the left-hand in Fig. 5, and showing the slot-forming reducing-tool in its normal, inoperative position. Fig. 7 is a detail sectional elevation of the toggle devices shown in Fig. 6 for holding the slot-forming reducing-tool or saw in either of its extreme positions. 20 Fig. 8 is a detail elevation, showing the slot-forming reducing-tool, or saw, in its working or operative position. Fig. 9 is an enlarged sectional end elevation of the turret-mechanism and of the gearing for actuating the 25 tool-carriers mounted therein, the view being taken looking from the right-hand in Fig. 5. Fig. 10 is a detail elevation of a portion of the carrier for the slot-forming tool or saw, and of the spur-gear mounted on said carrier. Fig. 11 is a transverse section of the 30 same, the section being taken in line *b—b*, Fig. 10, looking in the direction of the arrow, and illustrating the loose connection for permitting the spur-gear to rotate independently of the carrier after said carrier has received a partial rotative movement. Fig. 35 Fig. 12 is an enlarged detail end elevation, similar to that shown in Fig. 9, and illustrates the operation of the coupling and uncoupling 40 cams (hereinafter described) for throwing one of the tool-operating spur-gears into and out of engagement with its respective internal gear; in this view one spur gear only is illustrated but in each of two positions in its 45 orbit of revolution incident to the rotation of the carrier, and in different positions of rotation about its own axis. Fig. 13 is a transverse section of the same, the section being taken in line *c—c*, Fig. 12, looking in 50 the direction of the arrow. Fig. 14 is an enlarged detail sectional end elevation, looking from the right-hand of the machine, of a portion of the turret-mechanism and the blank-feeding mechanism, the view illustrating the positive and negative feed-indi-

cating cams and the oppositely-movable feed segments for positively controlling the movements of the blank, and showing the parts in their normal positions, all of which devices will be hereinafter more particularly 70 referred to. Fig. 15 is a section of the same, the section being taken in line *d—d*, Fig. 14. Fig. 16 is a detail sectional end elevation of the feed-indicating cams and the feed-operating devices, (shown in Fig. 14,) representing 75 the devices in their working positions, portions of the frame and of the operating parts being removed. Fig. 17 is a detail sectional elevation of the oppositely-movable feed-members of the blank-feeding mechanism, the parts being illustrated in their working positions. Fig. 18 is an enlarged detail side elevation of the latches, and of a portion of the operating connections for actuating the 80 shaping devices supported upon the turret. Figs. 19 to 23, inclusive, are detail sectional side elevations, illustrating successive steps in the operation of my improved latch and of starting-arms co-operative therewith, and 85 will be hereinafter more fully referred to. Fig. 24 is a detail sectional plan of a pair of latches constructed in accordance with my 90 present improvements and supported in a suitable latch-block or frame. Figs. 25 to 95 28, inclusive, are sectional end elevations of the turret-mechanism and latches, and illustrate successive steps in the operation of, and successive positions of the respective tools for, forming a character or impression-face in a segment of the face of the blank, all 100 of which will be hereinafter fully described in detail. Fig. 37 is a diagrammatic view of the latches and the starting-arms secured to the tool-carriers, and illustrates, as will 105 be hereinafter more fully pointed out, the manner in which a determined plurality of the carriers of a series of independently-rotatable carriers may be selected without actuating the others of said series. Fig. 38 is 110 a diagrammatic view, illustrating the connections from the key-levers of the machine to the respective latches controlled thereby. Fig. 39 is a similar diagrammatic view of a portion of the keys and their connections 115 with the corresponding latches. Fig. 40 is a diagrammatic view, illustrating the different paths through which a tool-carrier may be caused to travel after its rotation has been begun by one of a number of different starting-arms, and the different points in such paths at which the movements of the carrier 120 begin and stop. Figs. 41 to 43, inclusive, illustrate the movements of the respective side-cutting or facing-tools, and the die, or 125 character-impressor, traveling, respectively, in curtate and prolate hypotrochoidal paths and in a pure hypocycloidal path, as will be hereinafter more fully described. Figs. 44 to 55, inclusive, illustrate in detail the opera- 130

tion of forming characters or impressions (shown for purposes of illustration as type-characters) of varying sizes and configurations in the face of a blank, as will be fully 5 described hereafter in this specification.

Similar characters of reference designate like parts in all the figures of the drawings.

Any suitable framework may be employed for the purpose of operatively mounting 10 the several mechanisms and devices necessary for carrying out my invention. I have shown herein at 2 a base having supporting legs or feet; and a main-frame and an end frame are shown, respectively at 3 15 and 4 as fixedly secured to said base, the connection of the parts being made in any suitable manner, as by means of bolts. The main-frame 3 is illustrated in the present case as secured to the base adjacent to one 20 side thereof, and as extending above and over the same substantially to the other side thereof, so as to form an overhanging frame structure, the main member thereof being designated by 3, as before stated, while the 25 upper or transverse portion thereof is designated by 3', and the depending arm or hanger at the extreme end of said cross-piece 3''. One end of the main driving-shaft 5 of the machine is illustrated as 30 journaled in a bearing carried at the extreme lower end of the hanger 3'', while the other end of such shaft is represented as journaled in a similar manner in a bearing in the upper side of the frame 4, an intermediate 35 bearing being also shown as formed in the upright 3 of the main-frame and as alined with said previously mentioned bearings for the purpose of supporting such driving shaft at a point between its aforesaid supporting 40 bearings.

The illustrated elements for setting off a longitudinal portion of the face of a blank to obtain a solid impression or type-blank, and for subsequently forming an impression 45 or type-character in the face of such blank, comprise means adapted to sustain a suitable blank; reducing means operative for reducing a longitudinal portion of the face of the blank, and preferably in the form of a 50 slot-forming reducing-tool for transversely slotting the face of said blank, to thereby form an impression or type-blank at the side of said slot; character-forming means—such as a suitable character-impressor or die—for 55 forming a character or impression in the face of the impression-blank, and means for actuating these devices into and out of engagement with the said blank. In addition to these operating means I also find it 60 advantageous to include with the impressor one or more side-cutting tools, adapted, respectively, for shaping the face of a portion of the blank which may be an isolated blank segment to mark therein a division or cut 65 extending toward, and preferably through,

the side of the blank, and shaving-tools adapted, respectively, for cleaning or shaving the face of the blank-segment before the formation of an impression therein, and for shaving the face of such impression after 70 it has been impressed or otherwise suitably shaped in the material of the said blank-segment. I also prefer to include, in connection with the before mentioned elements, a pair of cutters so disposed that they will 75 trim the sides of the finished impression and remove the surplus metal forced out by the action of the impression-forming dies, and thereby bring the sides of the impression within the planes of the sides of the blank. 80 It will be obvious, therefore, that in connection with a suitable blank-sustaining means I make use of a plurality of shaping-tools, shown as type-shaping tools, which are operative in the construction illustrated 85 to conjointly form a character in a type-blank segment of the face of a typebar-blank.

In the preferred form thereof herein shown, all of the several shaping devices or tools hereinbefore enumerated are advantageously embodied in a turret-mechanism, which includes as its essential features a rotary-turret—such, for instance, as illustrated at T in the drawings—and a plurality 90 of shaping-tools, of which each tool is either operative for forming a characteristic device or type-character in the face of a blank, when in operative relation with such blank, or else said tools are organized for operation 95 in groups as herein shown, the tools of a group operating in succession upon a blank to shape therefrom the character corresponding to the tools of such group. It is, however, distinctly to be understood that 100 my invention is not limited to the production of type-characters, which are shown simply for the purpose of illustration, but includes within its scope the formation of any series of desired impressions in the face 105 of a suitable blank.

The turret is shown in the drawings as having a shaft 5, which constitutes the main driving-shaft of the machine and is journaled in the framework in the manner hereinbefore outlined. The several devices which are illustrated in the present case as carried by the rotary turret and as constituting parts of the type-forming mechanism are—a slot-forming reducing-tool for transversely 115 slotting the face of the typebar-blank; two sets of revoluble side-cutting tools, the tools of each of which sets are adapted, respectively, to face opposite upper edges of successive type-blanks and thereby form type-blanks having the areas of their faces less than the areas of their bases; a tool for removing burs and shaving the faces of the successive type-blanks after the operation of 120 the respective cutting-tools thereon; a set of 125

revoluble character-impressors of dies adapted, respectively, to form corresponding characters in the faces of the respective type-blanks subsequently to the operation of the 5 shaving-tool upon the faces of said blanks; and a tool for shaving the faces of the respective finished type-characters.

For the purpose of carrying the revoluble type-shaping tools the turret T is illustrated 10 herein as having five tool-carrying shafts, designated, respectively, by 6, 7, 8, 8', and 8'', these shafts being mounted in corresponding journals in the opposite ends or heads of the turret, this turret being represented in 15 the present case as a skeleton structure for the purpose of permitting the free operation of the starting members or arms carried by said shafts, as will be hereinafter fully described. Each of these shafts is shown as 20 disposed for rotation in parallelism with the others.

At the left-hand ends of the respective shafts 6, 7, 8, 8', and 8'', the type-shaping devices are shown in the drawings as mounted 25 for operation. The tools carried by the shaft 6 are in the nature of cutters, as illustrated at r, and these cutters are shown herein as separate members carried in channels radiating from the center of a tool-head 12, 30 which is also fixedly secured to the shaft 6; and these cutters are capable of radial adjustment in the channels of the tool-head, for the purpose of regulating the cut to be 35 made by the respective tools when brought into operative relation with the typebar-blank. In the present case the cutters are shown as held securely in position for adjustment by means of clamping screws 12'.

The shaft 7 is illustrated, in the drawings 40 as carrying a series of cutters s which correspond, in the present instance, in number and circumferential positions with the respective cutters r carried by the shaft 6. The cutters r and s, as well as the character-impressors or 45 dies carried by the shafts 8, 8', and 8'', are also represented as mounted for rotation and orbital movement in the same plane, so that when the typebar-blank is held stationary, the respective cutters and die will operate 50 upon the same type-blank segment. The cutters s are also held in place, in this instance, in the same manner as the cutters r—that is, by means of clamping screws 13' engaging the cutters seated in channels in a 55 tool-head 13.

The character-forming tools or dies may be fixedly secured to, or formed integral with, their respective die-carriers—such as 14, 14' and 14'', and for the purpose of forming a 60 great variety of characters each die-carrier is represented herein as having thereon twice as many character - impressors or dies as either of the tool-heads 12 and 13 has cutters. Three die-carriers are illustrated in the drawings 65 as necessary for the purpose of accom-

modating the dies corresponding to the type-characters and other devices which are chiefly essential to practical type composition. Each of the dies, (which dies are herein represented by t,) has a characteristic device in intaglio or indentation, so that, when brought into separate relation with a type-blank, such die will form the corresponding character in cameo or relief in the face of such type-blank.

For the purpose of maintaining the type-shaping tools against movement transversely of their plane of orbital movement, and also the respective shafts, tool-heads, die-carriers, and connected parts, hereinafter more 70 particularly referred to, the contiguous transverse bearing faces of these several rotative parts are in close engagement with corresponding coöperative stop-shoulders, or similar members, fixedly carried by the turret, as 75 will be evident by reference, for example, to Figs. 13 and 15, in which the coöperative members are illustrated as closely fitted, so that the shafts, etc. will be incapable of movement longitudinally of the turret. In 80 a substantially similar manner the main driving-shaft 5, to which the turret is fixedly secured, is also maintained against movement longitudinally relatively to its supporting bearings, thus insuring a very accurate 85 positioning of the type-shaping tools relatively to the turret and longitudinally of the axis of rotation thereof throughout the operations necessary to the formation of characters in the typebar-blank.

The slot-forming reducing-tool which I prefer to employ is illustrated herein as a saw u having its cutting edge substantially concentric with the axis of the turret when the saw is in its inoperative position, and this 105 tool is shown as supported by an oscillatory shaft or carrier—such as 15, (see Figs. 6, 7 and 8,)—which, in the present case, is represented as carried by the turret-mechanism in substantially the same manner as the shafts 110 for the cutters and dies are supported. This slot-forming tool or saw is also preferably pivoted to the turret, in this case at the left-hand end thereof, and is so carried by the shaft 15 as to be capable of movement between its two extreme, or working and idle, 115 positions.

In the drawings, the saw proper is represented as secured to a frame 17, this frame being the part which is pivoted to the turret 120 in the manner just described; and said frame is also provided with a substantially elliptical central opening in line with the shaft 15, and through which passes an eccentric 15'. This eccentric is secured to said shaft and its diameter is of substantially the same length as the minor axis of the elliptical opening in the saw-carrier, so that the carrier will rest on said eccentric at all times, and, in its oscillatory movements about the pivot 17', will be 125 130

positively controlled by said eccentric, and hence by the oscillation of the shaft 15. It will be apparent, therefore, and especially by reference to Fig. 8, that if the shaft 15 is given a partial rotation, the saw will be tipped in either the one direction or the other relatively to the pivot 17', and will be brought nearer to, or carried further away from, the face of the typebar-blank, and, moreover, this approach, or withdrawal, will be effected by the gradual change in the position of the eccentric.

All of the tool-carrying shafts, it will be understood, will be positively held in their normal positions in some suitable manner, as, for instance, by means of spring-pressed brake-shoes—such as 19—normally bearing against flattened portions of the peripheral faces of the respective shafts 15, 6, 7, 8, 8' and 8'', as clearly shown in Fig. 4. The normal positions of the shaft 15 and the eccentric 15' are shown in Fig. 6, and in this view the saw *u* is in its idle position, ready to be thrown into engagement with the typebar-blank. For the purpose of maintaining these parts against rotative movement when the saw is in either of its extreme positions, a toggle connection is illustrated herein as joining the turret-mechanism and the carrier or shaft 15. This connection is preferably a resilient one, and is represented herein as embodying a spring—such as 18—suitably secured at one of its ends to a fixed part of the turret-mechanism, and at its other end to one end of the curved link 18', the other end of which link is pivoted to the fixed arm or toggle-member 18'', secured to the shaft or carrier 15. The toggle-members are so connected and organized, relatively to the shaft and to the turret that when in either one of its extreme positions the saw will be held there by a toggling action, and accidental movement of the saw toward the opposite extreme position will be prevented. It will be obvious now that if the shaft 15 be partially rotated, the brake-shoe 19 will be carried off from the flattened face of such shaft, and the saw will be carried at the same time beyond its normal path of movement and into position for transversely slotting the typebar-blank, as shown in Fig. 8.

It will be understood, of course, that the main driving-shaft and the turret are continuously rotated while the machine is in operation, as, for instance, by means of the band-wheel 22.

For the purpose of selectively bringing any desired tool, secured to any carrier, or shaft, into position for operating upon the typebar-blank, I make use of starting means the preferred form of which will now be described. As has been hereinbefore indicated, one of the principal functions of the present invention is the selection of a plurality of determined type-shaping tools, mounted on

different carriers, and the operation of such selected tools into engagement with the typebar-blank to form a type-character corresponding to the tools so chosen.

It will be obvious that, in order to organize within as small a compass as possible, a type-forming turret-mechanism, capable of forming a great variety of type-characters, or similar devices, it is desirable to employ only so many tools auxiliary to the dies, or character-impressors, as are indispensable for the proper formation of the several types which the machine is designed to produce. In the present case, therefore, while I have illustrated three die-carriers, each carrying an equal number of dies, but two cutter-carriers are represented, and each of these has but half as many tools as any individual die-carrier, and hence it will be apparent that the cutters of either cutter-carrier should be capable of coöperating with the dies of any die-carrier. This end is attained by devices which are adapted for causing the rotation of any one or more of the cutter-carriers and die-carriers without operating the others, and the means by which a plurality of tools supported by different carriers may be selectively brought into working position will now be described.

The machine illustrated in the present application is illustrated as having thirty-six dies upon each die-carrier, and the operation of each die is controlled, in the present instance, by an individual finger-key on a suitable key-board, which will, therefore, be provided with one hundred and eight different keys, each of which is adapted for selectively bringing into operative position a particular set of coöperative members or impressors for forming its individual type-character.

The key-board of the machine is fully illustrated in Fig. 1, and, as before stated, is furnished with a plurality of keys, each of which is designated in a general way by K, these keys being shown in the present case as secured to corresponding key-levers 23 (see Fig. 3) pivoted near their rear ends to the base of the machine in any well-known manner, as, for instance, by being pivoted on the fulcrum-bar 24, and held in place by the retaining bar 24', said keys and key-levers being also shown as returned to their normal positions against a suitable back stop after actuation by means of springs 25 as is customary.

Each of the key-levers is shown in the drawings as operatively connected by means of a suitable connecting-rod—such as 260—with a respective angle-lever 261 mounted for oscillation upon a main carrier-rod—such as 262—secured between, and adapted to form a brace for, a pair of rear frame-pieces—such as 263 and 263'—which are illustrated in the drawings as fixed at their lower ends to the base of the machine, and at their upper ends to the cross-piece 3' of the main

frame-member. It will be apparent, therefore, that this carrier-rod will support one hundred and eight independently-oscillatory angle-levers, disposed side by side, (see Fig. 1,) and controlled, respectively, by the corresponding finger-keys of the key-board. The frame-pieces 263 and 263' are also represented as supporting a series of secondary carrier-rods—such as 264—which are illustrated as eighteen in number in the present case. Each of these rods preferably carries an equal number of angle-levers—such as 265—also independently oscillatory on such rod, so that there will be in this instance six such angle-levers for each of the rods. These carrier-rods extend the entire distance between the frame-pieces 263 and 263', but it will be evident that each of the secondary angle-levers 265 should be in the plane of the corresponding angle-lever 261 from which it is operated. These primary and secondary levers are illustrated as connected by means of wires or rods 266, and it will be noticed (see Fig. 18) that the rods to the several rows of secondary angle-levers, as well as such angle-levers themselves, are dissimilar, the rods 266, connected to the lower rows of angle-levers 265, being shorter than those connected to the upper rows, while the angular positions of the arms of the angle-levers 265 also vary from the lower to the upper row of the series. As each of the secondary angle-levers is in the plane of its respective primary angle-lever 261, it will be seen that all of the connecting-rods or wires will be in parallelism in the direction of pull, so that there will be no interference. It will be understood that the several angle-levers 265 will be held against movement along their respective carrier-rods in some suitable manner, as, for instance, by means of stop-collars—such as 265'. (See Fig. 1.)

Each of the several rows of secondary angle-levers illustrated in the drawings is intended to be operative for actuating a corresponding series or row of rock-shafts—such as 267—which in turn control the release of a corresponding series or tier of latches for selectively bringing the tools of the turret-mechanism to their working positions. These rock-shafts are shown as journaled at their opposite ends in the frame-pieces 263 and 263', one hundred and eight of these rock-shafts being represented, divided into eighteen rows, containing six rock-shafts each, and disposed in an arc of a circle, as are also the secondary carrier-rods and angle-levers, and the latches. Each of these rock-shafts is also illustrated as having fixedly secured thereto a rock-arm 267' in the plane of the secondary angle-lever from which it is operated, a suitable connecting-rod or pull-wire of proper length, being illustrated at 268 as connecting said parts. It is, therefore, obvious that all of the wires 268

are also disposed in parallelism in the direction of pull, the two arms of each of the angle-levers 265 being preferably in parallel planes, so as to prevent interference between the two series of wires 266 and 268. Each 70 of the rock-shafts is also shown as provided with a latch-tripping arm—such as 267"—fixedly secured thereto in any convenient position for operating the latch which it is designed to control, and it will be apparent 75 that the position of the tripping-arm longitudinally of its rock-shaft is entirely independent of the position of the rock-arm by which said shaft and tripper are actuated, so that, by the described construction of parallel main and secondary carrier-rods, rock-shafts and alined angle-levers, rock-arms and connecting wires, it is possible to actuate a particular latch at any desired point longitudinally of the rock-shaft from which it is 80 tripped, and to assemble in any preferred position, in longitudinal direction relatively to the rock-shafts, a group of latches having any desired orbital location relatively to the turret-mechanism with which they are intended to coöperate. In the present case, the group of latches is shown as divided into eighteen superposed orbital rows located substantially centrally of the frame-pieces 263 and 263'; and the trippers 267" are also 85 divided into eighteen series of six trippers to each series, and located directly in the rear of the latches. It will be noticed, however, (see Fig. 18,) that the latch-trippers and their respective actuating rock-arms are of 90 various lengths, and that the lengths of those arms of the angle-levers with which said rock-arms are connected also vary in inverse order, so that all of the latch-trippers may be actuated by the exertion of substantially the 95 same amount of force at the keys.

The latches for operating the tools of the turret-mechanism are represented in the drawings as carried by a latch-frame or latch-block, (designated in a general way by 29,) 100 which may be formed integral with, or fixedly secured to, the main upright 3 of the frame-work. This latch-carrying frame is preferably provided with end-pieces—such as 29' and 29"—concentric with the axis of 105 the turret-mechanism, and formed with a plurality of series of pairs of registering slide-ways, radially disposed, relatively to the turret axis, and corresponding in number with the number of orbital series of latches. 110 In these slideways the latches are shown as carried for reciprocation into and out of operative relation with the turret-mechanism. (See Figs. 19 to 24.)

The end-pieces 29' and 29" serve as stops 115 for limiting the movements of the latches; and the latches which I prefer to employ are represented herein as operative to two successive working positions, and as having a pair of catches adapted, respectively, for 120

successive engagement by a pair of stops, which are shown as formed by the shoulders 290 and 290' of the end-piece 29'. Each latch is preferably a duplex one and spring 5 actuated, having longitudinally-separated catches, one of which is carried by the main member and the other by the auxiliary member of the latch, this auxiliary member being shown as resilient transversely relatively to 10 the main member. The main member of the latch is designated herein by 28, and the auxiliary member of the duplex latch (which auxiliary member will also be termed the auxiliary latch) is shown as a resilient 15 arm 280 secured to the main latch and having a catch 280' adapted to be engaged by the stop 290 when the latch is released by the tripper 267''. The duplex latch is operative 20 to two successive working positions, one of which is limited by the catch 280', and the other by an ordinary stop or catch—such as 28'; and the actuation of this latch is effected by a pair of successively-operative 25 tripping means, viz., one of the trippers 267'' and a starting-arm on the turret, these acting to impart successive tripping movements to the latch.

The slideways in the end-pieces 29'' are of such width as to permit the main latch to 30 be actuated transversely at the rear end thereof for the purpose of releasing or tripping the same and for restoring it to its normal position. A spring 30 is illustrated as normally holding the main latch up in position 35 to permit a stop-shoulder thereof—such as 28''—to engage the co-operative shoulder of the end-piece 29'' of the latch-frame. A strong spring of helical form is shown at 31 as coiled around a pin 31', movably connected with the main member of the latch so 40 as to permit a slight yielding of these parts relatively to each other, and working in a suitable aperture passing through the end-piece 29'', in parallelism with the slideway 45 adjacent thereto. This spring is operative for actuating the latch to project the same into the path of the turret-mechanism when the force of the spring 30 is overcome by the action of the tripper 267''. It will be noticed 50 (see Fig. 24) that the auxiliary latch is of relatively-small size as compared with the main member 28, and that this main latch is preferably recessed at one side thereof, the auxiliary member being secured to the main 55 latch in position to work in said recess with its forward end normally in line with the corresponding end of the main member.

In Figs. 38 and 39 I have illustrated diagrammatically the operating connection 60 between the finger-keys and the latches, Fig. 38 being a diagram for the entire key-board, while Fig. 39 represents but a portion of the keys and their connections. To these views, particularly, reference should be had for a

clear understanding of the key-operated latch 65 system.

The devices just described for governing the operation of the type-shaping tools from the keys constitute a permutation-controller system or connector system by means of 70 which the movements of a plurality of members or tools disposed in one predetermined or arbitrary manner may be governed by corresponding keys disposed in the same or any other arbitrary or predetermined manner; and not only is this the case but the operations controlled by the several keys may be permitted or changed so as to establish a different relationship between the keys and the tools, this changed relationship 75 resulting ordinarily either from a change in the disposition of the keys at the keyboard, or from a change in the disposition of the type-shaping tools, or from both. When any such change as this is to be made, of course it will 80 necessitate a reorganization of the connector elements, some of the old lines of controller connection being broken and new lines of control or connection established, this being done in the present case by changing the positions 85 and connections of some of the connector elements—such as the links and levers of the connector system—many of which will preferably be so constructed as to be interchangeable with one another. By employing 90 a controller or connector system substantially of this type the operation of the mechanism may be varied at will by simply changing the connections and the positions 95 of certain parts, and the same style of keyboard may thus be used with tools grouped in different ways, or different styles of keyboard may be employed without changing 100 the disposition of the tools. Not only is this the case where but a single group of tools is 105 employed, but it is also true when several independently-operable carriers are used to support different sets of tools. Usually it will be more convenient to change the grouping 110 of the keys and readjust the connections therefrom than to regroup the tools of a set.

For the purpose of bringing the turret-mechanism into operative relation with a latch which has been actuated by the depression of its respective key, each of the 115 shafts 15, 6, 7, 8, 8', and 8'' is shown in the drawings (see particularly Figs. 6 and 37) as having fixedly secured thereto one or more starting members or arms, designated by 120 320, 321, 322, 323, 324 and 325, each of these arms being provided with a starting finger—such as *w*—in position to be engaged by the inner end of the projected latch, and each one of the starting-arms carried by the die-carriers or shafts 8, 8', and 8'' is also represented as having a latch-replacing finger *w'* 125 for restoring the latch to its original position after being actuated thereby.

It will be apparent that the interposition of a latch into the path of any starting-arm will serve to actuate that arm, and to rotate the carrier to which it is secured; but as this action takes place only during the short interval of time in which the starting-arm is in engagement with the latch, it is evident that some other means must be employed to continue the actuation of the tool-carrier after the starting-arm has passed the latch. I prefer to utilize the initial partial rotation imparted to any tool-carrier by the latch and the starting-arm as the means for continuing the rotation of the carrier so started, until the selected tool secured to such carrier has completed its operation upon a typebar-blank; and I also make this initial partial rotation and the continuation of its rotation entirely independent of the operation of any other tool-carrier of the series.

In Figs. 9, 12 and 13 I have illustrated in detail means for continuing the initial rotation of each tool-carrier without affecting the operating of any other carrier mounted on the turret. In these views each of the shafts 15, 6, 7, 8, 8' and 8'' is shown as having a longitudinally-shiftable spur-gear mounted thereon. The several spur-gears carried by all of these shafts, except the first-mentioned one, are similarly constructed, and a description of one will suffice for all. That carried by the shaft 15 will be herein-after more particularly referred to. The spur-gears, mounted on the respective carriers 6, 7, 8, 8' and 8'', are designated, respectively, by 33, 41, 43, 43' and 43'', and each of these spur-gears or pinions is shown as held against rotative movement relatively to its shaft by means of guide-pins—such as 34—screw-threaded into said pinion and adapted to slide through transverse openings or recesses in a hub or collar—such as 35—secured to its shaft. This collar 35 limits the movement of the pinion in one direction, and a stop-pin is illustrated at 35' as limiting its reciprocation in the opposite direction, it being understood, of course, that the guide-pins 34 are maintained constantly in engagement with the walls of the lateral recesses in the flange on the collar 35, as seen in Figs. 12 and 13. As has been hereinbefore explained, the carrier 15 is oscillatory and has a partial rotative movement in each direction, and the longitudinally-reciprocatory spur-gear which is mounted thereon, and is designated herein at 151, is not shown as fixed against rotative or oscillatory movement relatively thereto, but instead is free to rotate relatively to, and independently of the movement of, the shaft 15 after imparting a partial rotative movement thereto.

Referring especially to Figs. 9, 10, 11, 14 and 15, it will be seen that the spur-gear 151 is illustrated as formed with a long barrel 151', which slides on a corresponding hub

portion 152 integral with, or fixedly secured to, the shaft 15, the outer end of which hub is adapted to form a stop for limiting the movement of the pinion 151 in one direction, by the engagement therewith of the inner end 70 of the chambered barrel. The movement of the pinion in the other direction is limited, as described with reference to the pinions carried by the shafts, by a pin 35'. The barrel portion of the pinion carries the 75 positive and negative cams (hereinafter described) for controlling the movements of the blank-feeding mechanism, and is also provided with a pivoted pawl, which is shown at 153 as working in a peripheral slot in said 80 barrel, (see Fig. 11,) this pawl being normally held in engagement with a flattened portion of the hub 152, said flattened portion terminating in a stop-face or tooth—such as 152'—adapted to be engaged by the end of 85 the pawl at the proper point in the rotation of the pinion, this pawl being normally held against the periphery of the hub 152, as by means of the spring 154. It will be obvious that when the shaft 15 is given a partial rotation by its starting-arm and the co-operating latch, in the direction indicated by the arrow in Fig. 11, the spur-wheel, which in its normal position holds the pawl at the point indicated in said figure, will be partially rotated 90 also by the engagement of the tooth 152' against the end of the pawl 153, but that the pinion will be free to continue its rotation indefinitely in the same direction if acted upon by other suitable driving means. Each of 100 the pinions 151, 33, 41, 43, 43' and 43'' is adapted to be brought into engagement with an internal gear, concentric with the axis of the turret mechanism, for the purpose of continuing the rotation of such pinion and its 105 carrier after the rotation thereof has been started by the interposition of a latch into the path of a starting-arm secured to such carrier. As a means for bringing a desired pinion into mesh with its respective internal gear, and for carrying it out of engagement therewith, each of such pinions is shown herein as having secured to the hub thereof a pair of cams, designated, respectively, by 36 and 37, the former of which has its cam-face 110 inclined in one direction, and is adapted for coupling its pinion with a co-operative driving internal-gear, and the latter of which has its cam-face inclined in the opposite direction, and is so disposed as to release said pinion from its driving internal-gear after the 115 operation of the tool which is brought into operative relation by the rotation of such pinion has been completed.

The standard 3 of the main-frame of the 125 machine is illustrated in the present case as constituting a gear-carrier adapted for carrying three main driving internal-gears concentric with the axis of the turret-mechanism and having different pitch-circles. These in- 130

- ternal-gears are shown at 38, 380 and 381 as mounted in the gear-carrier, and as suitably held against movement relatively thereto, the gears being so located, and the ranges 5 of the longitudinal reciprocations of the pinions being such, that when any one of the pinions is slid to its extreme position to the left the teeth of the pinion will mesh with those of its respective internal gear.
- 10 For the purpose of bringing any pinion into mesh with its internal gear without undue friction, the teeth of each pinion are illustrated (see Figs. 11 and 13) as beveled for a considerable peripheral distance on that face 15 of the pinion which is adjacent to its corresponding internal-gear, while the teeth of each driving internal-gear are shown as similarly beveled for a considerable distance on that side of said internal-gear which is adjacent to its coöperative pinion. (See Fig. 9.)
- It will be apparent that some suitable resistance face must be opposed to the action of each of the cams 36 and 37 in order that the operation of coupling the respective pinions with, and uncoupling them from, their internal gears may be properly effected. These resistance faces are shown in the drawings as oppositely-inclined cam-faces 39' and 40', formed by oppositely beveling the inner 25 faces of a pair of segmental cams—such as 39 and 40—which cams are illustrated as located in parallelism with each other and in fixed relation with the standard 3 of the main-frame. (See Figs. 9, 12 and 13.)
- 30 These segments may be separate from the standard 3 and secured thereto in any suitable manner, as by means of set-screws. (See Fig. 9.)
- In the normal operation of the turret- 40 mechanism each pair of cams 36 and 37 will be carried in an orbit by the turret and in operative relation with the cam-faces 39' and 40'. The coupling of any pinion with its internal-gear is dependent upon the fact that 45 when any starting-arm, operative with such pinion, is engaged by the latch the rotation of the pinion causes the cams 36 and 37 carried thereby to rotate therewith relatively to the turret, and thereupon, when the cam 50 36 comes opposite the cam-face 39', such cam will be forced up said cam-face, and hence the pinion will be slid along its shaft into mesh with its internal-gear. After a predetermined period of rotation of this pinion, the 55 cam 37, when it comes opposite the cam-face 40', is carried outward by said cam-face in a lateral direction opposite to the direction of movement just described with reference to the cam 36, and the pinion is uncoupled from 60 its internal-gear. (See Figs. 12 and 13.) The flattened faces of the carriers on which the pinions are mounted are so located that when any pinion is thrown out of engagement with its internal-gear the brake-shoe 19 will 65 engage such flattened face and prevent fur-

ther rotation of the carrier and its pinion. (See Fig. 4.)

As hereinbefore stated, the shafts 6 and 7, with their tool-heads 12 and 13, constitutes carriers for operatively supporting two series 70 of cutters, while the shafts 8, 8' and 8'' with their tool-heads 14, 14' and 14'', constitute carriers for three separately-rotative series of different dies or impressors; and as the pinions 33 and 41 mesh, respectively, with the 75 internal-gears 38 and 381, while each of the pinions 43, 43' and 43'' meshes with the internal-gear 380, (see Fig. 9,) it will be obvious that the first and second series of side-cutting tools and the several series of dies 80 will be actuated, respectively, in prolate hypotrochoidal, curtate hypotrochoidal, and pure hypocycloidal paths. (See Figs. 41, 42 and 43.)

The latches employed in the present case 85 have been hereinbefore referred to as divided into six orbital rows, having eighteen latches in each row; and the carriers 15, 6, 7, 8, 8' and 8'' also have been described as having one or more starting-arms for each. It will 90 now be seen, by references to Fig. 37 especially, that the present construction contemplates the employment of six starting members or arms for each of the first three carriers just mentioned, while but two such starting-members are secured to each of the die-carriers or shafts. The reason for this is that, in the machine illustrated in the drawings, it is intended that some one or more of the latches of each orbital row or series shall 95 100 be operative for starting rotating one starting-arm on each of the first three shafts actuated, viz., the saw-shaft and the two cutter-shafts. It will be obvious, however, that this need not necessarily be the case. The 105 latches are also shown as so disposed in orbital direction that all of the characters carried by a single die-carrier are controlled by the latches of two rows, the dies being so positioned around the periphery of each die-carrier that one series of alternating dies corresponds to one row of latches, and the other series of dies correspond to the next adjacent row of latches; and the starting-arms for each die-shaft are illustrated in the present 110 115 case as disposed not only in different parallel planes, which planes pass through the latches coöperative therewith, but as also having different radial positions, see Fig. 6, the distance between the working ends of the starting-fingers being the same as the distance between the dies on such shafts. By positioning the dies and the starting-arms in this manner, I am enabled to use twice the number of dies on each die-carrier that could be employed with starting-arms having the same radial position, as, with the construction just described, it will be apparent that the rotation of any die-shaft may be begun at either 120 125 one of two separated orbital points by a pair 130

of latches having exactly the same orbital position. In the present instance, the die-shaft 8 is shown as having two starting-arms controlled, respectively, by the two orbital 5 rows of latches, shown at the left in Fig. 37; while the die-carrier 8' is illustrated as provided with a pair of similar starting-arms in position for operation, respectively, by the latches of the central pair of orbital rows, 10 illustrated in said figure, and the carrier 8'' is represented as having its pair of starting-arms operative, respectively, by the latches of the right-hand pair of orbital rows, shown in said diagrammatic view. It will be obvious, moreover, that if no other provision 15 than that just described were made for selectively bringing the several die-carriers into operation, at each actuation of a latch all of the starting-arms comprised in the orbital 20 series, revoluble in their planes, passing through the side edges of the working faces of such latches would be engaged in succession, and hence the saw would be actuated, and the two cutter-carriers and the proper die-carrier would all be rotated.

For the purpose of obtaining a wider range of selection than would be afforded by such an organization, I have illustrated the latches (see Fig. 37) as having their working ends 30 divided into three parts or elements, each one of which may be considered as constituting a selector element, so that when all three of these elements are present in a latch, that latch will be operative for starting rotating 35 all of the starting-arms that lie within the orbital plane thereof, while, if any one or more of such elements are lacking, a starting-arm, or arms, lying within the orbital plane, or planes, of such missing portion, or portions, 40 would not be engaged by the latch and would not be brought into operative position.

All of the latches are, for convenience, illustrated herein as provided with the left-hand selector element, as seen in Fig. 37, and 45 each of the starting-members carried by the slotting-tool or saw-shaft is illustrated as having its working end in the path of this element. Moreover, the starting-members carried by the die-shaft 8 are represented also as 50 lying in the path of said left-hand selector element, as seen in said figure.

As I have found that it is not necessary that both cutters should be brought into operation for each letter, or character, which 55 the present machine is designed to form, many of the latches are illustrated as having one or both of the right-hand pair of selector elements thereof removed, as shown in Fig. 37, for the purpose of permitting the starting- 60 arm, or arms, lying in the plane, or planes, thereof to pass the latch while the turret is rotating, without engaging said latch and without being operated thereby. The omission of either, or both, of such right-hand selector elements of any latch will, of course,

be dependent entirely upon the nature of the letter, or character, controlled by such latch, it being apparent, for instance, that, if the central selector element is lacking, the second cutter-shaft 7—which carries the cutters for facing, or removing, the lower edges of the type-blank segments of the type-bar-blank—will not be actuated, and, hence, the lower edges of the faces of the type-formative blanks for such letters as "y", for example, will not be removed. If the extreme right-hand selector element, as seen in Fig. 37, is missing, then the cutter-shaft 6 will not be rotated, and, as this shaft carries the cutters for facing the upper edges of the faces of the type-blanks of the typebar-blank, it will be seen that the upper edge of a type-formative blank for such a letter as "f", for instance, would not be faced. If both right-hand selector elements are lacking, then neither of the cutter-shafts 6 and 7 would be brought into operation, and neither the upper nor the lower edge of the type-formative blank, for such a letter as "Q", for example, would be faced. Where all three of the selector elements are present, as in the case, for instance, with the latch "e", then both the upper and the lower edge of the type-formative blank therefor would be reduced by the cutting tools, and a type-blank having a relatively- 90 small face would be left for the action of the die corresponding to such letter.

The internal-gears 38, 380 and 381 have been described as constituting driving-gears for rotating the pinions operative with the two side-cutting-tool carriers, the die-carriers, and the saw-carrier, but while these form proper driving-gears for the tools of the turret-mechanism, they do not constitute suitable means for effectively locking the respective side-cutting tools and dies against slipping during the time when they are shaping a typebar-blank to form a type-character therein. For the purpose of preventing such slipping of the tools at the moment of operation, each of the internal gears is represented as preferably formed with a gear-segment radially adjustable relatively to the axis of the turret-mechanism, together with means for effecting such radial adjustment, relatively to the spur-gear, or gears, with which the respective internal-gears are adapted to mesh, and for holding the segment in position. I have shown such segments at 38', 380' and 381', as preferably hardened steel, or similar members, secured in vertical guide-ways formed by removing a portion of the inner vertical face of each of the internal gears or annuli, adjusting screws being illustrated at 52 for raising these gear-segments 110 to bring them into close mesh with their respective pinions and thus prevent slipping or backlash. (See Figs. 5 and 9.) These segments are also shown as alined with the longitudinal axis of the type-blank, so that the 115 120 125 130

locking of the tools against slipping will be effected at the proper moment.

For the purpose of adjusting the internal-gears about the axis of the turret relatively 5 to the gear-carrier to maintain the teeth of said gears in their proper positions relatively to the typebar-blank, each of the annuli 38, 380 and 381 is illustrated as having a shoulder 45 (see Fig. 3) formed by removing 10 a peripheral portion of such gear-carrier, or annulus, and these shoulders are represented as having fixedly secured thereto oppositely-disposed stop-rods, or pins, such as 46 and 47, respectively, the outer ends of these pins 15 being adapted to enter alined bores—such as 48 and 49—in the respective gear-carriers 38, 380 and 381. Adjusting screws are illustrated at 50 and 51 (see Figs. 1 and 3) as working in these bores, with their inner ends 20 in contact with the outer ends of the stop rods 46 and 47, so that, by the proper manipulation of said adjusting screws the internal gears may be independently adjusted slightly, to permit their teeth to be brought into 25 proper relationship with the longitudinal axis of the typebar-blank, and into proper mesh with the corresponding teeth of their respective pinions.

The terms "gear", "gearing", etc., as 30 herein used, include both the toothed and the frictional varieties, these terms are explained in Patent No. 399,746, granted to D. W. Dodson and F. H. Richards, March 19, 1889.

35 Any suitable means may be employed for holding the typebar-blank B in position to be operated upon by the tools of the turret mechanism. In the present case, this blank is illustrated as supported in a blank-carrier, 40 which is designated in a general way by C, and is in the nature of a slide-block, movable transversely of the machine in suitable ways and having an adjustable jaw to permit the engagement or release of the blank. The 45 main-jaw of the slide-block is shown herein at 53, and the auxiliary or movable jaw-carrier is illustrated at 54 as adapted for holding the blank firmly against the fixed jaw 53', suitable clamp-screws being shown 50 at 55 as passed through a shoulder 53'' of the slide-block for engaging such movable jaw and releasing the same. The ways which control the direction of movement of the blank-carrier are shown at 56 as suitable 55 guides bolted to the base of the machine, the feed-screw, represented herein as operative for advancing such blank-carrier, being illustrated at 57 as working in a longitudinal bore of the carrier, and as supported near its 60 right-hand end by a journal-bearing in the upright 3. For the purpose of maintaining the blank-carrier in operative relation with the feed-screw, said carrier is shown as having a spring-pressed locking-pin—such as 65 59—the inner end of which is adapted to

engage in the helical groove of said screw. When it is desired to move the slide-block a considerable distance along the feed-screw it is obvious that, first, the locking-pin should be retracted and drawn out of engagement 70 with the walls of said groove. (See Figs. 2 and 5.)

Beyond the bearing in the standard 3 the shaft of the feed-screw 57 is illustrated as having another bearing in an upright or 75 block—such as 400—carried by the base of the machine intermediate the members 3 and 4; and at its extreme right-hand end this feed-screw shaft is shown as having fixedly secured thereto a gear-wheel—such as 60—80 which may be held against movement transversely of the machine in any suitable manner. The teeth of this gear-wheel are in mesh with the teeth of an idle-wheel, which is shown at 61 as carried by a stud secured to 85 the upright 400, the teeth of this latter gear being also illustrated as in mesh with the teeth of a third gear-wheel 63 fixedly secured to a short spindle 630 rotatively mounted in bearings in the uprights 4 and 400. (See Fig. 5.) A ratchet-wheel is shown at 65 as in fixed relation with the spur-wheel 63; and a pair of gear-segments is illustrated at 650 and 651 as loosely mounted on the spindle 630 for oscillation thereon in opposite directions by means of a pair of co-operative gear-segments operative in opposite directions by the positive and negative feed-indicating cams, which will be described hereinafter. The gear-segment 650 95 is represented in the drawings (see Figs. 14 and 17) as carrying on an arm 650' thereof a spring-pressed pawl 652, normally held in engagement with the teeth of the ratchet-wheel 65, and the throw of the pawl is controlled by the conjoint action of the two gear-segments 650 and 651, the former of which constitutes a feed-member for the blank-feeding mechanism of which these devices 100 form parts, and the latter of which is in the nature of a feed-member-stop operative for 105 checking the movement of the segment 650 by the engagement of the stop-face 651' against a corresponding member or stop—such as 650''. As just stated, a second pair 110 of gear-segments is employed, and these are illustrated at 653 and 653' as fixedly secured to a pair of rock-shafts 654 and 654', mounted for oscillation in the uprights 3 and 400 of the main-frame. Each of the rock-shafts 654 and 654' is represented as provided with a rock-arm at its inner end, and substantially in the working plane of the respective indicating wheel carried by the turret, these rock-arms being shown at 655 and 655' as facing 125 toward each other and as bored for the reception of the outer ends of corresponding plunger-rods—such as 656 and 656'. The rock-shafts are also illustrated as carrying a pair of shorter arms 657 and 657' provided 130

with adjusting screws for controlling the pressure exerted upon the same by a pair of springs—such as 658 and 658'—adapted for normally holding the gear-segments in the 5 positions shown in Fig. 14. In this figure, and in Figs. 15 and 16, portions of the standard 3 are shown as cut away for the reception of a pair of pivoted members, or rock-arms—such as 659 and 659'—which control the outward movements of the respective plungers, and in return are restored to their normal 10 positions by such plungers.

The present machine is adapted to form characters having faces of different widths, 15 the width of such faces being controlled by the length of blank which is intermittently fed by the blank-feeding devices, and for the purpose of indicating the length of blank to be so fed for the formation of a letter, the shaft 15 is shown as carrying two peripheral series of indicating members or cams. The cams of these series are equal in number and are disposed, respectively, in corresponding peripheral positions, each cam-face of one 20 segment having its indicating portion complementary to that of the corresponding cam of the other series. These two series I term "positive" and "negative" cams, the positive cams being designated herein by 770, 771, 25 772, 773, 774, and 775, respectively, while the negative cams are indicated, respectively, by 780, 781, 782, 783, 784, and 785.

There being six cams in each of the two 30 series of indicating members just described, it will be apparent that the present machine is adapted to form characters of six different widths, and that any one of six different feed movements may be imparted by the feeding mechanism to the typebar-blank. If it is 35 assumed that the cams 770 to 775, inclusive, represent indications for type-characters varying from three to eight units in width, and that a unit of width is represented by the rotation of the ratchet-wheel 65 a distance corresponding to one tooth thereof, it will be 40 apparent that as the negative cams 780 to 785, inclusive, represent indications ranging from eight to three units, respectively, the sum of the indications of any pair of corresponding cams will always be equal to the 45 sum of the indications of every other such pair. Hence, it will be seen that the sum of the movements of the gear-segments 650 and 651, in either direction, will always be the 50 same—that is to say, the segment 650 will always be actuated by the proper positive cam a distance corresponding to the width of the character to be formed, while the segment 651 will be rotated a distance just sufficient to bring it into engagement with the 55 segment 650 when such latter segment has completed its indicating movement. Thus each of said segments constitutes a positive stop for the other, and the feeding of the 60 typebar-blank an exact predetermined dis-

tance is thereby assured. (See Figs. 16 and 17.)

As shown in Fig. 17, the actual work of rotating the ratchet-wheel 65 and actuating the typebar-blank intermittently to feed the 70 same transversely of the plane of rotation of the turret-mechanism, for presenting successive type-blank segments of said typebar-blank to the type-forming mechanism, is not performed by the segment 650, but the pawl 75 652 is merely drawn back by the same a proper distance, and the subsequent rotation of such segment and the return of the parts to their normal positions are effected by an actuator—such as 80—rotating with the 80 turret, which actuator comes into engagement with the cam-face 650''' of the arm 650', and thus positively actuates said arm to return all of the segments and their connected parts to the positions shown in Fig. 14. 85

By reference to Fig. 15 it will be noticed, as has been hereinbefore described, that the pinion 151, with which the indicating cams are shown as formed integral, is normally out of mesh with its respective internal gear; 90 and the two series of cams are also normally out of the respective planes of the rock-arms 659 and 659', these cams being so organized relatively to such rock-arms and to said pinion and its internal gear as to be carried 95 to the left, as seen in Fig. 15, into working position when the rotation of the shaft 15 is begun by one of its starting-members.

As the cams of each series just described are disposed in peripheral positions corresponding to their indicating values, so the latches controlling the operation of said cams are arranged in orbital direction according to the widths of the characters represented by such latches. This will be apparent by 100 reference to Fig. 37, in which the upper two transverse tiers of latches correspond to characters having a width of three units, the next four tiers to characters of four units, the next four tiers to characters of five units, the 105 next two tiers to characters of six units, the next five tiers to characters of seven units, and the lower tier to characters of eight units. It will be noted also that there are six latches having space-keys on the key-board, and 110 these latches represent, in a manner exactly similar to that just described, six different space-characters, of correspondingly-different widths which may be formed in a typebar-blank, these space-characters being employed as desired for spacing between words and at the beginning and end of each 115 paragraph.

As the ratios of indication of the several pairs of indicating members are different, 120 and as any desired pair of such members may be selectively brought into position to operate the feed member and the feed-member-stop, it will be evident that the movements of said feed-member and its stop will 125 130

be proportional to the indications of that pair of indicating members by which they are operated. In this connection the gear-segments 653 and 653' may be considered as feed-indicating segments, the segment 650 as the feeding-segment, and the segment 651 as the stop-segment of the series, the feeding-segment being operative for actuating, through its pawl, the blank-feeding 10 member or ratchet 65.

The operation of a machine embodying my invention and constructed as herein set forth is as follows: When the turret-operated tools are in their normal inoperative 15 positions and one of the keys of the keyboard is depressed the latch corresponding to such key will be released by the proper tripper and will be projected into the path of one of the starting-arms 320, secured to the 20 saw-carrier, as shown in Fig. 20. It being understood that the turret is continuously rotating in the direction indicated by the arrow in Fig. 25, it will be seen that the auxiliary member 280 of the latch will be engaged, first, by the starting-arm and will be pressed down until its catch 280' is released from engagement with the stop-shoulder of the end-piece 29' of the latch-frame, whereupon the force of the spring 31 will advance 25 the duplex latch still further into the path of the turret-operated tools, the forward movement being stopped by the engagement of the catch 28' against said end-piece 29'. It should be noted here that the starting-arms carried by the shaft 15 are slightly 30 longer than those secured to the other tool-carriers, the starting-arms 320 being operative for engaging any latch as soon as the same has been released by its tripper, while 35 the starting-members on the other carriers are somewhat shorter and cannot engage the latch until the same has been advanced from its first working position by the release of its auxiliary member 280. It is obvious, 40 of course, that the starting-arms carried by the saw-shaft will be longer than those carried by the other shafts in order that after a latch is projected the saw may be operated first and a proper sequence of operations 45 thus insured. As soon as the respective starting-arm 320 strikes the projected latch, said starting-arm will be rotated to the successive positions shown, for instance, in Figs. 22 and 27, and the partial rotation of 50 the shaft 15 in a direction opposite to the direction of rotation of the turret will cause the saw-frame and its connected parts to be thrown to the positions illustrated in Figs. 7, 8, 9, and 27, ready for forming a slot in 55 the typebar-blank. The cam-segment 39 occupies substantially the same orbital arc as that which includes the several series of latches within its limits, and, as soon as the rotation of the shaft 15 is begun, by the engagement of one of its starting-arms with a

latch, the coupling cam 36, which is rotated with the pinion 151, comes into engagement with the cam-face 39' of said cam 39, and riding up said face carries the pinion 151 inward and into mesh with the internal gear 70 381. The coupling of the pinion with its internal gear now being effected, the rotation of such pinion will be continued until the operation of the saw upon the blank is completed and the uncoupling cam 37 reaches 75 the cam-segment 40, when said uncoupling cam will ride up the cam-face 40' and will force the pinion 151 outward and out of mesh with the internal gear. It should be understood that the initial rotation of said 80 pinion is effected by the pawl 153 pressing against the tooth or face 152', but that, as soon as the starting-arm 320 passes the latch (the pinion and the internal gear being at this time in mesh) the orbital rotation of 85 said pinion will withdraw the pawl from engagement with said tooth, and the pinion will rotate idly about the shaft 15.

It will be understood that in a manner substantially similar to that just described the 90 rotation of the selected cutter-shafts and die-shaft will be commenced as soon as their starting arms come into operative relation with the projected latch, as will be apparent by reference to Figs. 28, 29 and 30, the pinions of such respective shafts being independently carried into engagement with the proper internal gears, respectively. 95

The die-shaft 8 is shown in Fig. 23 as operated by the depression of the key for the 100 formation of a selected character, and it will be noticed that, when the orbital movement of this shaft brings its starting-arm 323 to the position shown in this view, (see also Fig. 31,) the rotation of said starting-arm will be 105 begun. Before this arm is disengaged from the latch and passes the same, the replacing finger *w'* will exert a toggling action upon the latch, and will force the same back to its normal position, as shown in dotted lines in 110 said Fig. 23.

It will be apparent now that the movements of all the parts directly operative by engagement with a projected latch have been begun, and that, until the complete cycle of 115 operations necessary for the formation of a type-character, and for the return of the parts to their normal positions, has been completed, none of the starting-arms carried by the saw-shaft will be in a position to engage another projected latch. After the saw is thrown to its working position by the partial rotation of its starting-arm, the pinion 151 carrying the indicating cams continues 120 its movement in its orbit until said cams are 125 brought into engagement with the respective rock-arms 659 and 659', (see Fig. 16,) whereupon the proper positive and negative indicating cams corresponding to the projected latch cause the feeding-segment and 130

the stop-segment to be actuated into engagement with each other, (see Fig. 17,) and a moment later the actuator 80, carried by the turret, rides over the cam-face 650' and restores the feed devices to their normal positions, at the same time causing these devices to be actuated to feed the typebar-blank forward a distance corresponding to the width of the type-character controlled by the latch which has been actuated. Immediately after the feeding of the blank the saw engages the same and cuts in the blank a transverse slot of gradually increasing depth from the point to the heel of the saw, (see Figs. 8, 15 30 and 31,) thus setting off a type-blank segment of the typebar-blank in advance of such slot. As soon as the saw cuts the slot in the type-bar blank, a rock-arm—such as 320'—fixedly secured to the shaft 15, comes 20 into contact with a replacing pin or stud—such as 80'—secured to the left-hand bearing of the depending arm 3", (see Fig. 5,) and the shaft 15 is partially rotated in a direction opposite to the direction of its actuation by 25 the engagement of the latch with the starting-arm 320, and the saw and its frame are returned to their normal positions. (See Figs. 6 and 32.) The first side-cutting tool which is operated, that is to say, the tool carried by the shaft 6 and corresponding to the key depressed, then faces one edge of the type-blank by its movement in a prolate hypotrochoidal path (see Figs. 32 and 41); and thereafter the second side-cutting tool 30 corresponding to such key, viz., the tool carried by the shaft 7, faces the opposite edge of the type-blank by its movement in a curtate hypotrochoidal path. (See Figs. 33 and 42.) As soon as the head of a type-blank has been brought thus to a proper form, a bur-removing, shaving tool—such as that shown, for instance, at x, (see Figs. 6 and 34)—comes into contact with the face of the type-blank, and carries off any bur 40 that may have been thrown up by the saw, and also removes any coating which may be present upon the face of such type-blank, thereby preventing the clogging of the die and malformation of the type by the loose pieces of metal, and also exposing a 45 smooth bright surface adapted to form a clear-cut type-character when acted upon by the character-forming die. Immediately after this shaving operation the proper character-forming die, also corresponding to the key struck, which die is carried by one of the shafts 8, 8' and 8", comes into engagement with the bright surface of the type-blank, and by its movements in a pure hypocycloidal path forms in the blank a type-character, the face of which is in a plane perpendicular to the vertical axis of the blank and common to the faces of all of the other type-characters which might be formed in such

type-blank by the other dies carried by any 65 one of said die-shafts. (See Figs. 35 and 43.)

In order to secure absolute uniformity in the positioning of the faces of the finished types, and to thereby maintain the faces of successive type-characters in a common 70 plane, I have shown herein at y a second shaving tool, the edge of which extends to a slightly greater distance from the axis of the turret than the edge of the tool x, and is, therefore, enabled to cut in a greater orbit, the edge 75 of the tool y being so positioned upon the turret that it shaves the faces of the finished type-characters to a uniform depth, it being understood that only an extremely minute turning is removed by this cutter. (See Fig. 36.)

By reason of the disposition of the axes of the respective shafts 15, 6, 7, 8, 8' and 8" at a plurality of different distances from the axis of the turret, (see Fig. 9,) it will be 85 apparent that the pinions carried thereby will travel in a plurality of paths of different diameters, and these pinions will come successively into alinement, respectively, with the type bar-blank just prior to the action 90 upon such blank of the respective tools controlled by such pinions, each of such pinions being brought into close, meshing engagement with the teeth of its respective gear-segment 38', 380' or 381', thus locking the 95 type-shaping tool, corresponding to such pinion, against slipping in circumferential direction while operating upon the type bar-blank.

In order to bring each of the finished types 100 to a thickness corresponding to that of the body of the typebar-blank, and thereby permit the proper assembling of a number of finished typebars in a form, I have shown herein at z and z', respectively, a pair of 105 cutters suitably mounted, as, for instance, upon the arched frame-piece 401, and in position and adapted for trimming the longitudinal sides of the finished type to remove surplus metal forced sidewise by the 110 action of the character-forming die. (See Figs. 2, 3, 5 and 50.)

The movements of the two series of side-cutting tools and of the dies are illustrated in detail in Figs. 41 to 43, inclusive. In 115 Fig. 41 it will be seen that the pinion 33 meshes with the internal gear 38, which has the largest pitch-circle, and that as the cutting edge of the side-cutting tool lies within the pitch-circle of the pinion, the cutting-tool will travel in a prolate hypotrochoidal path and will face one edge of the blank by a progressive forward movement. In Fig. 42, however, the pinion 41 meshes with the internal gear 381, which has the smallest 125 pitch-circle, and the cutting edge of the side-cutting tool is extended beyond the pitch-circle of the pinion, so that the edge

of the blank opposite to that shown in Fig. 41 is faced by a cutting action exerted in a direction opposite to the direction of rotation of the turret, the edge of the tool moving in a curtate hypotrochoidal path; and hence, the movement of the cutting edge to the rear after it has faced the blank is continued sufficiently far to permit it to be carried a considerable distance away from said blank, so as to prevent interference of the cutter with the type-blank segment operated upon after its work is completed. In Fig. 43 the pinion 43 meshes with the internal gear 380, and the position of the face of the die is defined by the pitch-circle of the pinion, so that when the die comes into engagement with the blank it forms the type-character by a movement in a pure hypocycloidal path.

20 In the drawings of the present case the cam-segments 39 and 40 have been shown as so positioned that in some cases each of the several tool-carrying shafts will rotate twice upon its axis before the corresponding pinion 25 is uncoupled from the internal gear with which it is in mesh, while in other cases the same shafts will accomplish three rotations on their respective axes before this uncoupling operation is effected. This will be obvious 30 by reference more particularly to Fig. 40, in which the latches are shown as having such positions, relatively to the cams 39 and 40, that the upper four rows of latches are operative for starting the rotation of these 35 shafts at such points that the uncoupling of their respective pinions from the corresponding internal gears will not be accomplished until such shafts have made three rotations on their axes, while the lower fourteen rows 40 are represented as disposed at such points relatively to the cams that the uncoupling of the pinions from their internal gears is effected as soon as the shafts and pinions have made two rotations.

45 The action of the several tools for operating upon the typebar-blank to form a typebar is illustrated in detail in Figs. 44 to 55, inclusive. Each of the blanks is preferably formed with a shoulder or inclined face—such as 90—by 50 removing a portion of the end of said blank, it being understood that this shoulder is duplicated at the other end of the blank, as will be seen by reference to Fig. 51. This provides the necessary backing or support 55 for the terminal characters of the typebar, and also forms a means for spacing such characters at the proper distance from the usual column-separating rules. After the blank has been fed a distance corresponding 60 to the width of the face of the type to be formed, the reduced portion or slot 91 is formed by the saw, and a type-blank 89 is thus set off in advance of such slot. The tool *r* then faces the upper edge of the type-blank 65 —as shown at 92—and the under side of the

blank is faced in the opposite direction—as at 93—by the cutter *s*. It will be obvious now, by reference to Fig. 46, that the head of the type-blank so shaped is of pyramidal, or frusto-pyramidal, form, the face of the blank 70 being of considerably less area than the area of the base of such blank. The face of the type-blank is next traversed by the shaving tool *x* for the purpose of removing any burs that may have been thrown up by the saw, 75 and also for removing a thin shaving therefrom. The die *t*, being brought into action, then compresses the upper portion or face of the pyramid, or frusto-pyramid, shaped by the action of the previously-operative tools, 80 to form a type-character corresponding to the die employed.

In Fig. 49 the faces of the finished types are illustrated as being shaved by the cutter *y*, for the purpose of bringing the surfaces of all 85 the types of the typebar into a common plane. In Fig. 50 the action of the cutters *z* and *z'* is illustrated for trimming the sides of finished types and removing the surplus metal forced beyond the planes of the sides 90 of the typebar-blank by the action of the character-forming dies, in order that the finished typebars may be properly assembled and locked up in a form.

In Figs. 52 to 55, inclusive, I have illustrated, on a larger scale, the action upon the typebar-blank of tools suitable for shaping successive type-blanks to form several different kinds and widths of characters. The cutters *r* operative to face the upper edges of 100 the type-blank are not all of the same character, and by varying the lengths of the cutting edges of these tools and the positions of the same, I am enabled correspondingly to vary the facing of the upper edges of type-blanks 105 of the same or different sizes. In a similar manner, the tools *s* are adapted to face the lower edges of type-blanks of a greater or less length to a greater or less extent. It should be noted here that the lengths of the cutting 110 edges of these tools correspond to the length of blank fed for the formation of the corresponding type-characters. Moreover, the cutting edges of the tools are disposed in such positions as are best adapted for the proper 115 formation of the characters corresponding thereto. The blank for forming the letter "H" may be faced (see Fig. 52) by a cutter *r*, adapted for removing a small portion 95' of the upper edge of such blank 95, while the 120 lower edge is faced at 95" by the removal of a portion of the blank extending almost to the base thereof. In this case the top of the letter extends almost to the edge of the blank, and hence, the type-formative face of the 125 type-blank must be located in a corresponding position. The next succeeding blank is shown at 96 as formed by the action of two like cutters *r* and *s*, having their cutting edges of less length than those by which the 130

edges of the blank 95 are faced. In this case the type-formative surface of the type-blank is centrally disposed relatively to the longitudinal sides of the typebar-blank, as the letter "e" requires but a small centrally-positioned face as compared with that needed for the letter "H". The type-blank 97 is represented as shorter than the first but longer than the second type-blank. In this case the letter "y" is to be formed, and the upper edge thereof is shown faced substantially like the upper edge of the blank 96, but the lower edge thereof is represented as reduced obliquely to the axis of the typebar-blank to form the slanting face 97". The type-blank 98 is illustrated as of less length than any of the three last referred to, and the cutting tools *r* and *s* therefor shape the type-blank in such a manner as to form a pyramidal blank having its apex below the surface of the typebar-blank, the faces formed by the cutting tools being designated, respectively, by 98' and 98".

It will be apparent from the foregoing that the side-cutting tools correspond to the respective letters which they are adapted to aid the dies in shaping, each of the cutters, with a few exceptions, having its cutting edge of the characteristic length which the typebar-blank is fed for the production of the particular type corresponding to such cutter.

In Figs. 54 and 55 the respective characters are shown as formed by the action of the appropriate dies upon the corresponding blanks, illustrated in Figs. 52 and 53. The displacement of the metal and the consequent filling of the saw slots are clearly illustrated; and the fourth character is shown as having its face a considerable distance below the face of the other characters, this fourth type-character being the shortest blank or "space" character.

Such a machine as that which I have described is adapted to form substantially all of the characters most commonly employed in commercial mechanical type composition, and to produce from suitable ductile metallic typebar-blanks typebars each having a succession of individually-characteristic, composed types of proper relative sizes selectively assembled to form accurately-spaced words.

While the various character-shaping tools are illustrated as mounted to travel in an orbital path, yet, it is obvious, they may be arranged to move in paths other than that shown and described without departing from my invention.

It is also manifest that various changes can be made in the disposition and construction of the various shaping-tools, and that the latch mechanism could be variously modified; and I, therefore, wish it distinctly understood that my invention is not limited to

the devices particularly described and illustrated.

Having thus described my invention, what I claim is—

1. The combination with a plurality of movable driven-members independently operable in curvilinear paths; of a driving selector operable for starting a determined plurality of said driven-members in operation in said curvilinear paths.

2. The combination with a plurality of movable driven-members independently operable in curvilinear paths; of a driving selector operable for starting a determined plurality of said driven-members in operation independently in said curvilinear paths.

3. The combination with a plurality of movable and independently-rotatable driven-members; of a driving selector operable for starting in independent rotation a determined plurality of said driven-members.

4. The combination with orbitally-movable and independently-rotatable driven-members; of a selector operable for starting in rotation a determined plurality of said driven-members.

5. The combination with a plurality of movable and independently-rotatable driven-members; and with a plurality of starting-members carried for rotation and movement in unison, respectively, with said respective driven-members; of a selector operable for engaging said starting-members to thereby start rotating a determined plurality of said driven-members.

6. The combination with a plurality of movable and independently-rotatable driven-members; and with a plurality of starting-members carried for rotation and movement in parallel planes and in unison, respectively, with said respective driven-members; of a selector operable for engaging said starting-member to thereby start rotating a determined plurality of said driven-members.

7. The combination with an orbital series of orbitally-movable and independently-rotatable driven-members; and with a series of starting-members carried for rotation and orbital movement in unison, respectively, with said respective driven-members; of a selector operable for engaging said starting-members to thereby start rotating a determined plurality of said driven-members.

8. The combination with an orbital series of orbitally-movable and independently-rotatable driven-members; and with a series of starting-members carried for rotation and orbital movement in unison, respectively, with said respective driven-members; of a selector operable for successively engaging a determined plurality of said starting-members to thereby start in rotation a determined plurality of said driven-members.

9. The combination with a series of movable

- and independently-rotatable driven-members; and with a series of starting-members carried for rotation and movement in unison, respectively, with said respective driven-members; of a selector operable to successively start in rotation a determined plurality of said starting-members and thereby the driven-members, at corresponding points in their path of movement.
- 10 10. The combination with an orbital series of orbitally-movable and independently-rotatable driven-members; and with a series of starting-members carried for rotation and orbital movement in a determined plurality of planes and in unison, respectively, with said respective driven-members; of a selector operable for successively starting in rotation a determined plurality of said starting-members, and thereby the driven-members, located in a determined plurality of parallel planes.
11. The combination with a series of movable and independently-rotatable driven-members; and with a series of starting-members carried for rotation and movement in a determined plurality of parallel planes and in unison, respectively, with said respective driven-members; of a key-operated selector having a determined plurality of selector elements disposed, respectively, in the corresponding respective planes of movement of a determined plurality of said starting-members and operable for successively starting in rotation the starting-members and thereby the driven-members, in such respective planes.
12. The combination with a plurality of movable and independently-rotatable driven-members; of a plurality of driving selectors having each one of a portion of said selectors operable for starting in rotation a determined number of said driven-members, and having each remaining selector operable for starting in rotation a determined plurality of separately-movable driven-members.
13. The combination with a plurality of movable and independently-rotatable driven-members; and with a determined number of starting-members for each of said driven-members, respectively, and carried for rotation and orbital movement in unison with its respective driven-member; of a plurality of selectors having each one of a portion of said selectors operable for starting in rotation a determined number of said starting-members, and having each remaining selector operable for starting in rotation a determined plurality of separately-rotative starting-members.
14. The combination with a plurality of movable and independently-rotatable driven-members; and with a determined number of starting-members for each of said driven-members, respectively, and carried for rotation and movement in unison with its respective driven-member; of a plurality of selectors having each one of a portion of said selectors operable for starting in rotation a determined number of said starting-members, and having each remaining selector operable for starting in rotation a determined plurality of separately-rotative starting-members.
15. The combination with a plurality of movable and independently-rotatable driven-members; and with a determined number of starting-members for each of said driven-members, respectively, and carried for rotation and movement in unison with its respective driven-member; of a plurality of independently-operative selectors having each one of a portion of said selectors operable for starting in rotation a determined number of said starting-members, and having each remaining selector operable for starting in rotation a determined plurality of separately-rotative starting-members.
16. The combination with a plurality of movable and independently-rotatable driven-members; of a plurality of transversely-separated series of starting-members, each series having its starting-members carried for rotation and movement in unison with its respective driven-member; of a plurality of selectors, one for each respective series of starting-members, and each operable for starting in rotation a determined plurality of the starting-members of its respective series.
17. The combination with a plurality of movable and independently-rotatable driven-members; of a plurality of starting-members disposed in transversely-separated sections, each one of said sections having a respective starting-member carried for rotation and movement in unison with each respective one of a determined number of the aforesaid driven-members, and one of said sections comprising a series of starting-members carried for rotation and movement in unison, respectively, with correspondingly respective driven-members; and a plurality of selectors, one for each respective section, and having one of said selectors operable for starting in rotation a determined plurality of the starting-members of the aforesaid series.
18. The combination with a plurality of movable and independently-rotatable driven-members; of a plurality of transversely-separated series of starting-members, each series having its starting-members carried for rotation and movement in unison, respectively, with the respective driven-members of a determined plurality of the aforesaid driven-members; and a plurality of transversely-separated series of selectors, one series for each respective series of starting-members, and each series of selectors having each of its selectors operable for starting in rotation a

determined plurality of the starting members of its respective series of starting-members.

19. The combination with a series of movable and independently-rotatable driven-members; of a plurality of transversely-separated series of starting-members, each series having its starting-members carried for rotation and movement in a determined plurality of parallel planes and in unison, respectively, 5 with the respective driven-members of a determined plurality of the aforesaid driven-members; and a plurality of transversely-separated series of key-operated selectors, one series for each respective series of starting-members, and each series of selectors having each of its selectors provided with a determined number of selector elements disposed, respectively in the corresponding respective planes of a determined plurality of the starting-members of its respective series of starting-members and operable for successively starting in rotation the starting-members in such respective planes.

20. The combination with a rotatable and 25 orbitally-revoluble driven-member; of a pair of starting-members carried for rotation and orbital movement in parallel planes and in unison with said driven-member, and a pair of separately-operative selecting members disposed, respectively, in the respective orbital planes of said starting-members, and operable, respectively, for starting said respective starting-members in rotation, and one pair of said two pairs of members having 30 its members disposed so as to lie in different relative positions in orbital direction when either of such members is in engagement with the corresponding member of the other pair.

21. The combination with a rotatable and 40 movable driven-member; of a pair of starting-members carried for rotation and movement in parallel planes and in unison with said driven-member, and having different relative rotative positions; and a pair of separately-operative selecting members disposed, 45 respectively, in the respective planes of said starting-members, and having corresponding positions, and operable, respectively, for starting said respective starting-members in rotation.

22. The combination with a rotatable and 50 orbitally-revoluble driven-member; of a pair of starting-members carried for rotation and revolution in parallel planes and in unison with said driven-member, and having different relative rotative positions; and a pair of 55 separately-operative selecting members disposed, respectively, in the respective orbital planes of said starting-members, and having corresponding orbital positions, and operable, respectively, for starting said respective starting-members in rotation.

23. The combination with a rotatable and 60 orbitally-revoluble driven-member; of a pair 65 of starting-members disposed transversely of

the driven-member, and fixedly secured to said driven-member at longitudinally-separated points, and having different relative rotative positions; and a pair of separately-operative selecting members disposed, respectively, in the respective orbital planes of said starting-members, and having corresponding orbital positions, and operable, respectively, for starting said respective starting-members in rotation.

24. The combination with a blank-carrier; of a character-forming mechanism embodying a series of independently-operative carriers, and a series of complementary character-shaping tools secured, respectively, to 70 said respective carriers; a carrier-actuating selector operable for starting a determined plurality of carriers, for driving their respective tools in working paths; means for continuing the working movement of each of 75 such carriers; and means for stopping the working movement of each of such carriers at the end of a predetermined period.

25. The combination with a blank-carrier; of a character-forming mechanism embodying a series of carriers independently-rotatable in parallelism, and a series of complementary character-shaping tools secured, 80 respectively, to said respective carriers for rotation and movement in a common plane; 85 a carrier-rotating selector operable for starting in rotation a determined plurality of carriers, for actuating their respective tools in corresponding working paths; means for continuing the rotation of each of such carriers; and means for stopping the rotation of 90 each of such carriers at the end of a predetermined period of rotation.

26. The combination with a blank-carrier; of a character-forming mechanism embodying a series of carriers independently-rotatable in parallelism, and a series of complementary character-shaping tools secured, 95 respectively, to said respective carriers for rotation and movement in a common plane; 100 a carrier-rotating selector operable for starting in rotation a determined plurality of carriers, for actuating their respective tools in corresponding working paths; means for continuing the rotation of each of such carriers; and means for stopping the rotation of 105 each of such carriers at the end of a predetermined period of rotation.

27. The combination with a blank-carrier; 110 of a character-forming mechanism embodying a series of carriers independently-rotatable in parallelism, and a series of complementary character-shaping tools secured, 115 respectively, to said respective carriers for rotation and movement in a common plane; 120 a carrier-rotating selector operable for starting in rotation a determined plurality of carriers, for actuating their respective tools in corresponding working paths; means for continuing the rotation of each of such carriers; and means for stopping the rotation of 125 each of such carriers at the end of a predetermined period of rotation.

means operative by the starting of such respective carriers for continuing the rotation of such carriers; and respective means for stopping the rotation of such respective carriers at the end of a predetermined period of rotation.

28. The combination with a blank-carrier; of a character-forming mechanism embodying a plurality of carriers independently 10 rotatable in parallelism, and a respective series of character-impressors secured to each respective carrier for rotation and movement in a plane common to the other series; a plurality of carrier-rotating selectors each 15 operable for starting a determined carrier rotating, for actuating a determined character-impressor in a working path; means for continuing the rotation of such carrier; and means for stopping the rotation of such carrier 20 at the end of a predetermined period of rotation.

29. The combination with a blank-carrier; of a character-forming mechanism embodying a pair of side-cutting-tool carriers and a 25 plurality of die-carriers all independently-rotatable in parallelism, a respective series of side-cutting tools secured to each respective side-cutting-tool carrier, and a respective series of dies secured to each respective die-carrier for rotation and movement in a plane common to the side-cutting tools; a plurality of carrier-rotating selectors each 30 operable for starting a determined number of side-cutting-tool carriers and a determined 35 die-carrier rotating for actuating a determined plurality of corresponding tools in corresponding working paths; means for continuing the rotation of each of such carriers; and means for stopping the rotation of each 40 of such carriers at the end of a predetermined period of rotation.

30. The combination with a blank-carrier; of a character-forming mechanism embodying a slot-forming reducing-tool, a pair of 45 side-cutting-tool carriers and a plurality of die-carriers all independently rotatable in parallelism, a respective series of side-cutting tools secured to each respective side-cutting-tool carrier, and a respective series of dies 50 secured to each respective die-carrier for rotation and movement in a plane common to the side-cutting tools and parallel with the plane of movement of the slot-forming reducing-tool; a plurality of carrier-rotating selectors 55 each operable for actuating the slot-forming reducing-tool, and for starting a determined number of side-cutting-tool carriers and a determined die-carrier in rotation for actuating a determined number of corresponding 60 tools in corresponding working paths; means for continuing the rotation of each of such carriers; and means for stopping the rotation of each of such carriers at the end of a predetermined period of rotation.

65 31. The combination with a blank-carrier;

of a character-forming mechanism embodying a pair of side-cutting-tool carriers and a plurality of die-carriers all independently rotatable in parallelism, a plurality of transversely-separated series of starting-members, 70 each series having a pair of starting members carried for rotation and movement in unison, respectively, with said respective side-cutting-tool carriers, and each series having also a starting-member carried for rotation and 75 movement in unison with a different die-carrier, a respective series of side-cutting tools secured to each respective side-cutting-tool carrier, and a respective series of dies secured to each respective die-carrier for rotation and 80 movement in a plane common to the side-cutting tools; a plurality of series of selectors, one respective series for each respective series of starting-members, and each selector operable for starting in rotation a determined plurality 85 of the starting-members of its respective series of starting-members, and thereby rotating the corresponding carriers; means operative by the starting of such carriers for continuing the rotation thereof; and means 90 for stopping the rotation of said carriers at the end of a predetermined period of rotation.

32. The combination with a character-forming mechanism embodying a series of independently-operative carriers; of a series of complementary character-shaping tools secured, respectively, to said respective carriers; a carrier-actuating selector operable for starting a determined plurality of carriers for driving their respective tools in working paths; means for continuing the working movement of each of such carriers; means for stopping the working movement of each of such carriers at the end of a predetermined period; and feeding mechanism operable by said character-forming mechanism, and adapted for intermittently feeding a blank transversely of the plane of movement of said character-forming mechanism, for presenting 100 successive segments of said blank to the said mechanism.

33. The combination with a pair of simultaneously-operative indicating members; of feeding mechanism embodying a feed-member and a feed-member-stop oppositely-movable, respectively, by said respective indicating members, proportionally to the indications of such indicating members, and into engagement with each other.

34. The combination with a pair of simultaneously-operative indicating members having a fixed ratio of indication; of feeding mechanism embodying a feed-member and a feed-member stop oppositely movable, respectively, by said respective indicating members proportionally to the indications of such indicating members, and into engagement with each other.

35. The combination with a pair of simul-

taneously-operative indicating members; of feeding mechanism embodying a feed-member and a feed-member-stop oppositely oscillatory and operable, respectively, by said 5 respective indicating members, proportionally to the indications of such indicating members, and into engagement with each other.

36. The combination with a pair of simultaneously-rotative indicating members having 10 a fixed ratio of indication; of feeding mechanism embodying a feed-member and a feed-member-stop oppositely movable, respectively, by said respective indicating members, proportionally to the indications 15 of such indicating members, and into engagement with each other.

37. The combination with a pair of indicating members operative in unison, and having 20 a fixed ratio of indication; of feeding mechanism embodying a feed-member and a feed-member-stop oppositely movable, respectively, by said respective indicating members, proportionally to the indications 25 of such indicating members and into engagement with each other.

38. The combination with a pair of indicating members carried for rotation and movement in unison, and having a fixed ratio of 30 indications; of feeding mechanism embodying a feed member and a feed-member-stop oppositely movable, respectively, by said respective indicating members, proportionally to the indications of such indicating members, and into engagement with each other. 35

39. The combination with a pair of indicating members fixed relatively to each other, and carried for rotation and movement in unison, and having their working faces defined by concentric arcs, to thereby express 40 a fixed ratio of indication; of feeding mechanism embodying a feed-member and a feed-member-stop oppositely movable, respectively, by said respective indicating members, proportionally to the indications of such indicating members, and into engagement with each other. 45

40. The combination with a series of pairs of simultaneously-operative indicating members, said pairs having, respectively, different ratios of indication; of feeding mechanism embodying a feed-member and a feed-member-stop operable, respectively, by the 50 respective indicating members of each respective pair and into engagement with each other, and having their movements opposite and proportional to the indications of the operating pair; and means for selectively bringing any pair of indicating members 55 into position to operate said feed-member and feed-member-stop.

41. The combination with a series of pairs of indicating members all carried for rotation in unison, said pairs having, respectively, different ratios of indication; of feeding mech-

anism embodying a feed-member and a feed-member-stop operable, respectively, by the respective indicating members of each respective pair, and into engagement with each other, and having their movements opposite 70 and proportional to the indications of the operating pair; and means for selectively bringing any pair of indicating members into position to operate said feed-member and feed-member-stop. 75

42. The combination with a series of pairs of indicating members all carried for rotation in unison, said pairs having, progressively-variable ratios of indication; of feeding mechanism embodying a feed-member and a feed-member-stop operable, respectively, by the respective indicating members of each respective pair, and into engagement with each other, and having their movements opposite 80 and proportional to the indications of the operating pair; and means for selectively bringing any pair of indicating members into position to operate said feed-member and feed-member-stop. 85

43. The combination with a pair of simultaneously-operative indicating members; of feeding mechanism embodying a pair of oppositely-oscillatory feed-indicating segments operable, respectively, by said respective indicating members, and a feeding-segment and a stop-segment operable, respectively, by said respective feed-indicating segments, proportionally to the indications of said indicating members, and into engagement with each other. 90

44. The combination with a pair of simultaneously-operative indicating members; of a pair of oppositely-oscillatory feed-indicating segments operable, respectively, by said respective indicating members; a feeding-segment and a stop-segment operable, respectively, by said respective feed-indicating segments proportionally to the indications of said indicating members, and into engagement with each other; a blank-feeding member operative by the return stroke of the feeding-segment; and a movable actuator operative for returning the feeding-segment to its normal position, and thereby actuating said blank-feeding member. 105 110

45. The combination with a character-forming turret-mechanism embodying a rotary carrier, of a series of character-shaping tools disposed in different rotative positions and carried for movement in unison with 115 said carrier, and a series of pairs of indicating members also carried for movement in unison with said carrier, each of said pairs corresponding in rotative position with a determined number of said shaping-tools and each pair having a different ratio of indication; of blank-feeding mechanism embodying a feed-member and a feed-member-stop operable, respectively, by the respective indicating members of each respective pair, and into 120 125 130

- engagement with each other, and having their movements in opposite directions and proportional to the indications of the operating pair; and means for rotating the carrier to bring any selected pair of indicating members into position to operate the feed-member and the feed-member-stop. 5 to said latches, and adapted, respectively, for successively engaging said respective catches; means for normally holding the main latch in its retracted position; and means for successively tripping said main and auxiliary latches 70
46. The combination with a latch operative to two successive working positions, and with a pair of catches carried by said latch; of a pair of stops in position and adapted, respectively, for successively engaging said respective catches in successive advanced positions; means for normally holding the latch 10 in its retracted position; and a pair of successively-operative tripping means for imparting successive tripping movements to the latch. 75
47. The combination with a spring-actuated duplex latch operative to two successive working positions, and with a pair of catches carried, respectively, by the respective members of said latch; of a pair of stops in position and adapted, respectively, for 15 successively engaging said respective catches in successive advanced positions; means for normally holding the latch in its retracted position; and means for successively tripping the respective members of the latch. 80
48. The combination with a spring-actuated duplex latch operative to two successive working positions, and with a pair of longitudinally-separated catches carried, respectively, by the respective members of said latch; of a pair of stops having corresponding positions longitudinally relatively to the latch, and adapted, respectively, for successively engaging said respective catches; means for normally holding the latch in its 20 retracted position; and means for successively tripping the respective members of the latch. 85
49. The combination with a spring-actuated duplex latch operative to two successive working positions, and having one of its members resilient transversely relatively to the other, and with a pair of catches carried, respectively, by the respective members of said latch; of a pair of stops in position and 25 adapted, respectively, for successively engaging said respective catches in successive advanced positions; means for normally holding the latch in its retracted position; and means for successively tripping the respective members of the latch. 90
50. The combination with a spring-actuated longitudinally-movable main latch carried for transverse movement at one end thereof, and having a catch; and with an auxiliary latch carried by the main latch, and resilient transversely relatively to the other end of said main latch, and having a catch separated longitudinally from said first-mentioned catch; of a pair of stops having corresponding positions longitudinally relatively 30 to the said latches, and adapted, respectively, for successively engaging said respective catches; means for normally holding the main latch in its retracted position; and means for successively tripping said main and auxiliary latches 95
51. The combination with a movable body; of a reducing-tool mounted thereon; means for oscillating said tool, and a resilient connection between the movable body and said tool. 100
52. The combination with a turret; of an oscillatory carrier; a reducing-tool actuated thereby; means for oscillating said carrier; and a toggle-connection between the carrier and turret. 105
53. The combination with a turret; of an oscillatory carrier; a reducing-tool actuated thereby; means for actuating said carrier; and a resilient connection between the carrier and turret. 110
54. The combination with a turret; of an oscillatory carrier movable between two extreme positions; a slot-forming reducing-tool pivoted to the turret, and carried by said carrier for oscillation thereby; means for oscillating said carrier, and thereby oscillating said reducing-tool; and a resilient toggle-connection between said carrier and turret, and normally operative for holding the carrier in either of its extreme positions. 115
55. The combination with a turret; of an oscillatory-carrier movable between two extreme positions, and having an eccentric; of a slot-forming reducing-tool pivoted to the turret, and mounted on said eccentric for oscillation thereby; means for oscillating said carrier, and thereby oscillating said reducing-tool; and a resilient toggle-connection between said carrier and turret-mechanism, 120 and normally operative for holding the carrier in either of its extreme positions. 125
56. The combination with a character-forming turret-mechanism embodying an oscillatory carrier movable between two extreme positions; a slot-forming reducing-tool pivoted to the turret-mechanism and carried by the carrier for oscillation thereby, a pair of rock-arms secured to the carrier, and a resilient toggle-connection between said carrier and turret-mechanism and operative for holding the carrier in either of its extreme positions; of means for rocking one of the rock-arms to carry the reducing-tool to its working position; and an actuator operative 130 for rocking the other rock-arm to return the reducing-tool to its normal position. 130
57. The combination with a character-forming turret-mechanism embodying an oscillatory-carrier movable between two extreme positions; a slot-forming reducing-tool pivoted to the turret-mechanism and carried by the carrier for oscillation thereby; a pair of rock-arms secured to the carrier, and a resilient toggle-connection between said car- 130

rier and turret-mechanism and operative for holding the carrier in either of its extreme positions; of blank-feeding means operative for feeding a blank transversely of the path of movement of the reducing-tool; means for rotating one of the rock-arms to carry the reducing-tool into engagement with the blank; and an actuator operative for rocking the other rock-arm to return the reducing-tool to its normal position.

58. The combination with a plurality of key-levers; of a plurality of independently-oscillatory parallel rock-shafts, one for each key-lever, disposed transversely of said key-levers and each rock shaft having a rock-arm in the plane of its respective key-lever, and also having a tripper operative with said shaft and in position for releasing its respective latch; operating connections from each key-lever to its rock-arm; a plurality of latches, one for each tripper; and character-forming mechanism, operative by said latches.

59. The combination with a plurality of key-levers; of a plurality of parallel carrier-rods, one for each key-lever; a plurality of transversely-separated independently-oscillatory angle-levers, a determined number journaled on each respective carrier-rod; a plurality of independently-oscillatory rock-shafts disposed in parallelism with said carrier-rod, one rock-shaft for each angle-lever, and each rock-shaft having a rock-arm in the plane of such angle-lever, and also having a tripper operative with said shaft and in position for releasing its respective latch; operating connections from each key-lever to its angle-lever and its rock-arm; a plurality of latches, one for each tripper; and character-forming mechanism operative by said latches.

60. The combination with a plurality of key-levers; of a main carrier-rod; a plurality of independently-oscillatory main angle-levers journaled on said carrier-rod, one for each key-lever; a plurality of secondary carrier-rods disposed in parallelism with said main carrier-rod; a plurality of transversely-separated independently-oscillatory secondary angle-levers, one for each main angle-lever, and disposed in the plane thereof, a determined number journaled on each respective secondary carrier-rod; a plurality of independently-oscillatory rock-shafts disposed in parallelism with the carrier-rods, one rock-shaft for each secondary angle-lever, and each rock-shaft having a rock-arm in the plane of such angle-lever, and also having a tripper operative with said shaft and in position for releasing its respective latch; operating connections from each key-lever to its main and secondary angle-levers and its rock-arm; a plurality of latches, one for each tripper; and character-forming mechanism operative by said latches.

61. The combination, with a plurality of independently-operable driven members, of a driving selector operable for starting a determined plurality of said driven members in operation.

62. The combination, with a blank-carrier for carrying a type-bar blank, of a plurality of die-carriers independently movable in a common path; type-shaping dies on said carriers; reducing means for reducing a transverse portion of the face of the blank without adding material to the face of an adjacent portion of the blank; and means for selectively starting any one of said die-carriers in operation without starting any other.

63. The combination, with a blank-carrier for carrying a type-bar blank, of a plurality of orbitally-movable and independently-rotatable die-carriers; type-shaping dies on said die-carriers and movable in a common plane; reducing means for reducing a transverse portion of the face of the blank without adding material to the face of an adjacent portion of the blank; and means for selectively starting any one of said die-carriers rotating without starting any other.

64. The combination with a plurality of orbitally-movable and independently-rotatable die-carriers, and means for sustaining a blank, of means for reducing a transverse portion of the blank without adding material to an adjacent portion; means for selectively starting any one of said die-carriers rotating during its orbital movement without starting any other die-carrier in rotation; and means for actuating the selected die-carrier and the sustained typebar-blank with relation to each other to effect a working engagement between the selected die and the typebar-blank and thereby form a type in the blank.

65. In a machine of the class specified embodying mechanism for actuating one of a pair of coöperative carriers relatively to the other to effect a working engagement between a type-die and a type-bar blank and thereby form a type in the blank, the combination, with a blank-carrier for the typebar-blank, of a plurality of orbitally-movable die-carriers independently rotatable in a plane transverse to the blank-carrier and adapted to coöperate selectively with the latter; type-shaping dies on said die-carriers; reducing means for reducing a transverse portion of the face of the blank without adding material to the face of an adjacent portion of the blank; and means for selectively starting any one of said die-carriers rotating without starting any other.

66. In a machine of the class specified embodying mechanism for actuating one of a pair of coöperative carriers relatively to the other to effect a working engagement between successively-selected type-dies and a type-bar blank and thereby form a series of types in the blank, the combination, with a

blank-carrier for the type-bar blank, of a plurality of orbitally-movable and independently-rotatable die-carriers adapted to coöperate selectively with said blank-carrier; 5 type-shaping dies on said die-carriers; reducing means for reducing a transverse portion of the face of the blank without adding material to the face of an adjacent portion of the blank; selecting means for selecting 10 type-dies on different die-carriers one at a time; and means for successively actuating said selected dies each to a working position.

67. In a machine of the class specified embodying mechanism for actuating one of a 15 pair of coöperative carriers relatively to the other to effect a working engagement between a type-die and a type-blank segment of a type-bar blank and thereby form a type in said type-bar blank, the combination, 20 with a blank-carrier for the type-bar blank, of a slot-forming reducing-tool for transversely slotting the face of said type-bar blank to form a type-blank in advance of said slot; a plurality of orbitally-movable 25 and independently-rotatable die-carriers adapted to coöperate selectively with said blank-carrier; type-shaping dies on said die-carriers; and means for selectively starting any one of said die-carriers rotating without 30 starting any other.

68. In a machine of the class specified embodying mechanism for turning one of a pair of coöperative carriers relatively to the other to effect a working engagement between a 35 type-die and a type-blank segment of a type-bar blank and thereby form a type in said type-blank, the combination, with a blank-carrier for the type-bar blank, of a slot-forming reducing-tool for transversely slotting 40 the face of said type-bar blank to form a type-blank in advance of said slot; a plurality of orbitally-movable and independently-rotatable die-carriers adapted to coöperate selectively with said blank-carrier; type-shaping dies on said die-carriers; and means for selectively starting any one of said die-carriers rotating without starting any other.

69. In a machine of the class specified embodying mechanism for actuating one of a 50 pair of coöperative carriers relatively to the other to effect a working engagement between a type-die and a type-bar blank and thereby form a type in the blank, the combination, with a blank-carrier for the type-bar blank, of a plurality of orbitally-movable die-carriers adapted to coöperate selectively with said blank-carrier; type-shaping dies on 55 said die-carriers and normally revoluble in inoperative relation with the blank and the blank-carrier; reducing means for reducing a transverse portion of the face of the blank without adding material to the face of an adjacent portion of the blank; and means for

selecting type-dies on different carriers for 65 operation one at a time.

70. The combination, with a type-forming mechanism embodying reducing means for reducing a transverse portion of the face of the typebar-blank without adding, material 70 to the face of an adjacent portion of the blank and a plurality of movable tool-carriers having type-shaping tools, and also embodying means for selectively starting any one of said tool-carriers in operation without 75 starting any other, of feeding mechanism controlled by said type-forming mechanism and adapted for intermittently feeding a type-bar blank for presenting successive type-blank segments of said type-bar blank 80 to the type-forming mechanism.

71. The combination, with a type-forming mechanism embodying reducing means for reducing a transverse portion of the face of the typebar-blank without adding material 85 to the face of an adjacent portion of the blank and a plurality of orbitally-movable and independently - rotatable die - carriers having type-shaping tools, and also embodying means for selectively starting any one of 90 said die-carriers in operation without starting any other, of feeding mechanism controlled by said type-forming mechanism and adapted for intermittently feeding a type-bar blank for presenting successive type-blank 95 segments of said type-bar blank to the type-forming mechanism.

72. The combination, with a type-forming mechanism embodying a plurality of orbitally-movable and independently-rotatable 100 die-carriers having type-shaping dies of different widths, and also embodying means for selectively starting any one of said die-carriers in operation without starting any other, of variable-feed mechanism controlled by 105 said type-forming mechanism and having variable-feed movements proportionate to the widths of the respective selected dies and adapted for intermittently feeding a type-bar blank for presenting successive type-blank 110 segments of said type-bar blank to the selected dies of the type-forming mechanism.

73. The combination, with type-forming mechanism embodying a plurality of type-shaping tools normally disposed in an arbitrary manner and operative for forming types 115 on the edge of a type bar-blank, of a plurality of keys also normally disposed in an arbitrary manner, a blank carrier for a typebar-blank, and a permutation-controller system 120 governed by said keys and controlling the operation of said tools and organized and adapted for permuting the operations controlled by said keys and controlling said tools.

74. The combination, with a type-forming 125 mechanism embodying a plurality of type-shaping tools normally disposed in an arbitrary manner and operative for forming type

on the edge of a typebar-blank, of a plurality of keys also normally disposed in an arbitrary manner, a blank-carrier for a typebar-blank, and a permutation system of connections controlled by said keys and controlling the operation of said tools and organized and adapted for permuting the connections between some of the keys and the corresponding tools.

75. The combination, with a type-forming mechanism embodying a plurality of type-shaping tools normally disposed in an arbitrary manner and operative for forming types on the edge of a typebar-blank, of a plurality of keys also normally disposed in an arbitrary manner, a blank-carrier for a typebar-blank, and a connector system controlled by said keys and controlling the operation of said tools and embodying a plurality of connector elements changeable to vary the normal connections between some of the keys and the corresponding tools.

76. The combination, with a type-forming mechanism embodying a plurality of type-shaping tools normally disposed in one arbitrary manner and operative for forming types on the edge of a typebar-blank, of a plurality of keys normally disposed in another arbitrary manner, a blank-carrier for a typebar-blank and a connector system controlled by said keys and controlling the operation of said tools and embodying a plurality of connector elements changeable to vary the normal connections between some of the keys and the corresponding tools.

77. The combination, with a type-forming mechanism embodying a plurality of type-shaping dies normally disposed in one arbitrary manner and operative for forming types on the edge of a typebar-blank, of a plurality of keys normally disposed in another arbitrary manner, a blank-carrier for a typebar-blank and a connector system controlled by said keys and controlling the operation of said dies and embodying a plurality of connector elements changeable to vary the normal connections between some of the keys and the corresponding dies.

78. The combination, with a type-forming mechanism embodying a plurality of type-shaping tools normally disposed in one arbitrary manner and operative for forming types on the edge of a typebar-blank, of a plurality of keys normally disposed in another arbitrary manner, a blank-carrier for a typebar-blank, and a connector system controlled by said keys and controlling the operation of said tools and embodying a plurality of connector elements interchangeable with one another to vary the normal connections between some of the keys and the corresponding tools.

79. The combination, with a type-forming mechanism embodying a plurality of independently-movable tool-carriers each having a plurality of type-shaping tools normally

disposed in one arbitrary manner and operative for forming types on the edge of a typebar-blank, of a plurality of keys normally disposed in another arbitrary manner, a blank-carrier for a typebar-blank, and a connector system controlled by said keys and controlling the operation of the tools of both sets and embodying a plurality of connector elements changeable to vary the normal connections between some of the keys and the corresponding dies.

80. The combination, with a type-forming mechanism embodying a plurality of orbitally-movable and independently-rotatable die-carriers each having a plurality of type-shaping dies normally disposed in one arbitrary manner, of a plurality of keys normally disposed in another arbitrary manner, and a connector system controlled by said keys and controlling the operation of said dies and embodying a plurality of connector elements changeable to vary the normal connections between some of the keys and the corresponding dies.

81. The combination, with a type-forming mechanism embodying a plurality of type-shaping tools normally disposed in an arbitrary manner and operative for forming types on the edge of a type bar-blank, of a plurality of keys also normally disposed in an arbitrary manner; a connector system controlled by said keys and controlling the operation of said tools and embodying a plurality of connector elements changeable to vary the normal connections between some of the keys and the corresponding tools; and feeding mechanism controlled by said type-forming mechanism and adapted for intermittently feeding a type-bar blank for presenting successive type-blank segments of said type-bar blank to the type-forming mechanism.

82. The combination, with a type-forming mechanism embodying a plurality of orbitally-movable and independently-rotatable type-shaping tools normally disposed in an arbitrary manner, of a plurality of resistant-starters controlling the rotation of said tools and located in positions corresponding to those of the tools; a plurality of keys also normally disposed in an arbitrary manner; and a connector system controlled by said keys and controlling the operation of said resistant-starters and embodying a plurality of connector elements changeable to vary the normal connections between some of the keys and the corresponding starters.

83. The combination, with a type-forming mechanism embodying a plurality of orbitally-movable and independently-rotatable die-carriers each having a plurality of dies disposed in an arbitrary manner, of a plurality of resistant-starters controlling the rotation of said dies and disposed in positions corresponding to those of the dies; a plural-

ity of keys also normally disposed in an arbitrary manner; and a connector system controlled by said keys and controlling the operation of said resistant-starters and embodying a plurality of connector elements changeable to vary the normal connections between some of the keys and the corresponding starters.

84. The combination with a plurality of normally inoperative members adapted to be conveyed periodically to the working point, of a driving selector operable for actuating a determined plurality of said members during their periodic movement and causing them to assume definite positions with relation to said working point.

85. The combination with a plurality of normally inoperative members adapted to be conveyed periodically to the working point, of a driving selector operable for independently actuating a determined plurality of said members during their periodic movement and causing them to assume definite positions with relation to said working point.

86. The combination with means for sustaining a blank, of a plurality of normally-inoperative independently-movable sets of impression devices, each of which sets embodies a group of such devices; means for conveying each set to the working point of the machine; means for selecting any one of the impression devices included in a set and causing it to assume an operative position at the working point and there subject a blank to compression; and means for moving said sets of impression devices and a sustained blank with relation to each other step by step to bring successive portions of the blank to the working point of the machine.

87. The combination with means for sustaining a blank, of a plurality of normally-inoperative independently-movable sets of impression devices, each of which sets embodies a group of such devices; means for conveying each set to the working point of the machine; means for selecting any one of the impressors included in a set and causing it to assume an operative position at the working point and there subject a blank to a rolling action; and means for moving said sets of impression devices and a sustained blank with relation to each other step by step to bring successive portions of the blank to the working point of the machine.

88. The combination with means for sustaining a blank, of a plurality of normally-inoperative independently-movable sets of impression devices, each of which sets embodies a group of such devices; means for conveying each set to the working point of the machine; key-levers and intermediate mechanism organized and adapted to render

one lever operative to control the movement of one set of impression devices to a working position or the movement of another set thereto; and means for moving said sets of impression devices and a sustained blank with relation to each other step by step to bring successive portions of the blank to the working point of the machine.

89. The combination with means for sustaining a blank, of a plurality of normally-inoperative independently-movable sets of impression devices, each of which sets embodies a group of such devices; means for conveying each set to the working point of the machine; a slot-forming tool; key-levers and intermediate mechanism organized and adapted to render one lever operative to control the movement of one set of impression devices to a working position or the movement of another set thereto; and means for moving said sets of impression devices and a sustained blank with relation to each other step by step to bring successive portions of the blank to the working point of the machine.

90. The combination with means for sustaining a blank, of a plurality of normally-inoperative independently-movable sets of impression devices, each of which sets embodies a group of such devices; means for conveying each set to the working point of the machine; a slot-forming tool; facing tools; key-levers and intermediate mechanism organized and adapted to render one lever operative to control the movement of one set of impression devices to a working position or the movement of another set thereto; and means for moving said sets of impression devices and a sustained blank with relation to each other step by step to bring successive portions of the blank to the working point of the machine.

91. The combination with means for sustaining a blank, of a plurality of normally-inoperative independently-movable sets of impression devices, each of which sets embodies a group of such devices; means for conveying each set to the working point of the machine; slot-forming and type-blank facing-tools; key-levers and intermediate mechanism organized and adapted to render one lever operative to control the movement of one set of impression devices to a working position or the movement of another set thereto; and means for moving said sets of impression devices and a sustained blank with relation to each other step by step to bring successive portions of the blank to the working point of the machine.

92. The combination with a plurality of normally inoperative members comprising blank reducing tools and type forming dies adapted to be conveyed periodically to the working point, of means for sustaining a

- blank at such point, and means for selecting a determinate number less than the full number of the said plurality of members and for causing them to work upon the blank.
5. 93. The combination with a plurality of normally inoperative members comprising blank reducing tools and type forming dies adapted to be conveyed periodically to the working point, of means for sustaining a blank at such point, means for selecting a determinate number less than the full number of the said plurality of members and for causing them to work upon the blank, and means for imparting a step by step longitudinal feed movement to the blank to bring successive type blank portions of the blank successively to the working point.
10. 94. In a type making mechanism, the combination with blank treating instrumentalities, of selective mechanism for selecting a plurality of instrumentalities to the exclusion of the others and means for rendering operative the selected instrumentalities.
15. 95. In a type-making machine, the combination with a selective mechanism comprising a plurality of keys, of a plurality of blank treating instrumentalities the complement thereof embodying a less number than said number of keys, and means for controlling the movement to an operative position of a plurality of determinate instrumentalities upon the actuation of a key and means for rendering operative the selected instrumentalities.
20. 96. The combination with a selective mechanism comprising a plurality of keys, of a plurality of members of less number than said number of keys, and means for controlling the movement to an operative position of a plurality of determinate members upon the actuation of a single key and means for rendering operative the selected instrumentalities.
25. 97. The combination with a plurality of type making instrumentalities, of a plurality of controlling keys, and intermediate connecting mechanism embodying a permutation connector, whereby one key controls more than one type-making instrumentality and means for rendering operative the selected instrumentalities, substantially as described.
30. 98. The combination with a blank carrier, of a plurality of series of normally inoperative impression devices, means for conveying these periodically into the working position in respect of said blank carrier, and means for selecting impression devices from a number of said series and bringing these serially into coöperative relation upon a blank in said carrier for the formation of a single character.
35. 99. The combination, with an orbital series of orbitally-movable and independently-rotatable driven members, of type shaping means on said driven members and key-operative means for selecting a plurality of said type shaping means and locating the same at the working point.
40. 100. The combination with a plurality of movable driven-members independently operable in curvilinear paths, of key-operated means for selecting a predetermined number of said driven members and in proper sequence inaugurating the movement thereof, and means for continuing said movement.
45. 101. The combination with a plurality of movable and independently-rotatable driven-members, of key operable selective devices for starting and rotating said driven-members means for returning the members to idle position after such actuation, and means for normally maintaining the same at such idle position.
50. 102. The combination with a plurality of series of tools, of selectors therefor, latches controlled by the selectors each when in its operative position for inaugurating the movement toward working position of a tool from each of a number of said series, a tool coöperative with any selected tool, means associated with said tool for engaging a selected latch for bringing said tool into working position and for advancing the latch into its operative position.
55. 103. The combination with a series of latches, of means for normally holding the latches retracted, means tending to advance the latches, means for stopping each latch at each of two positions of advance, a series of selectors each effective to release the latch and permit its partial advance, a plurality of series of tools, each series having a starting arm for engaging a latch when in its farthest position of advance, a tool coöperative with a tool from any of said series, and a starting arm carried thereby for engaging a partially advanced latch for moving said tool to its working position and for permitting the latch to advance to its farthest position.
60. 104. The combination with a plurality of orbitally movable rotatable tool carriers, of a blank carrier constructed for holding a blank within the orbit of said tool carriers, a series of tools carried on the respective tool carriers, one of said series being effective to work upon one side of the said blank, another series of said tools being effective to work upon another side of said blank, and another series of said tools being effective to work upon the face of said blank, and means for engaging each of said work carriers at a point so related to its orbit and the orbit of the working point of its tools in its rotation that said tools will be caused to engage the blank at its side faces and edge face respectively.
65. 105. In a device of the character specified,

the combination with a plurality of tool carriers, means for moving these in orbital paths, a blank holder, a series of tools for reducing one side of the blank, a series of 5 tools for reducing the other side of the blank, and a series of tools for reducing the face of the blank and carried by the respective 10 holders, a pinion carried by each of said tool carriers, and a series of internal gears of varying diameter for engaging said pinions and actuating the tools.

106. In a device of the character specified, the combination with a plurality of tool carriers, means for moving these in orbital 15 paths, a blank holder, a series of tools for reducing one side of the blank, a series of tools for reducing the other side of the blank, and a series of tools for reducing the face of the blank said tools being mounted upon said 20 tool carriers, and means for actuating said tool carriers.

107. The combination with a blank carrier, of a rotary die carrier, dies arranged at uniform angular distances about the die carrier and in the same plane, a turret for revolving said die carrier past said blank carrier, a pair of starting arms fast with said die carrier and disposed at an angular distance apart equal to that which separates the dies 30 and each in a different plane, a latch for each die, said latches being arranged in two series disposed in different planes, the members of one series being in position to be projected into the orbital path of one of said starting 35 arms and the members of the other series into that of the other of said arms, and means for continuing the rotation of the carrier after the engagement between the starting arm and latch.

108. The combination with a blank carrier, of a rotary die carrier, dies arranged at uniform angular distances about the die carrier and in the same plane, a turret for revolving said die carrier past said blank carrier, a pair of starting arms fast with said die carrier and disposed at an angular distance apart equal to that which separates the dies and each in a different plane, a latch for each die, said latches being arranged in two series 45 disposed in different planes, the members of one series being in position to be projected into the orbital path of one of said starting arms and the members of the other series into that of the other of said arms, means for continuing the rotation of the carrier after the engagement between the starting arm and latch, a series of tools coöperative with said dies in the formation of characters on the blank, said series having members equal in 50 number to the number of members in each latch series, and disposed at uniform angular distances apart, said angular distance being double that separating the dies, a carrier mounted on said turret for each of said series of coöperative tools, a starting arm fast with each of said coöperative tool carriers and arranged for engaging latches from 55 each series of latches.

109. The combination with a blank carrier and arranged in the same angular position, each for engaging one of said series of latches.

109. The combination with a blank carrier, of a series of rotary die carriers, dies arranged at uniform angular distances about each of said die carriers and in the same plane, a turret for revolving said die carriers past said blank carrier, a pair of starting arms fast with each of said die carriers and disposed at an angular distance apart equal to that which separates the dies on such carrier, all of said starting arms being in different planes, a latch for each die, said latches being arranged in series disposed in different planes, and there being two series for each die carrier, the members of each series being in position to be projected into the orbital path of its respective starting arm, means for continuing the rotation of a die carrier after 75 the engagement between one of its starting arms and a latch, a series of tools coöperative with said dies in the formation of characters on the blank, said series having members equal in number to the number of members 80 in each latch series, and disposed at uniform angular distances apart, said angular distance being double that separating the dies, a carrier for said coöperative tools mounted on said turret, starting arms fast with said 85 coöperative tool carrier and arranged in the same angular position, each for engaging one of said series of latches.

110. The combination with a blank carrier, of a series of rotary die carriers, dies arranged at uniform angular distances about each of said die carriers and in the same plane, a turret for revolving said die carriers past said blank carrier, a pair of starting arms fast with each of said die carriers and disposed at an angular distance apart equal to that which separates the dies on such carrier, all of said starting arms being in different planes, a latch for each die, said latches being arranged in series disposed in different planes, and there being two series for each die carrier, the members of each series being in position to be projected into the orbital path of its respective starting arm, means for continuing the rotation of a die carrier after the engagement between one of its starting arms and a latch, a plurality of series of tools coöperative with said dies in the formation of characters on the blank, each of said series being members equal in 100 number to the number of members in each latch series, and disposed at uniform angular distances apart, said angular distance being double that separating the dies, a carrier mounted on said turret for each of said 105 series of coöperative tools, a starting arm fast with each of said coöperative tool carriers and arranged for engaging latches from each series of latches.

111. The combination with a type-form- 110 115 120 125 130

ing mechanism embodying a plurality of selectable type-dies of different widths, of variable-feed mechanism controlled by said type-forming mechanism and having variable-feed movements that are multiples of a given unit of feed and are proportionate to the widths of the respective selected type-dies and adapted for intermittently feeding a type-bar blank for presenting successive portions of said blank to the selected type-dies of the type-forming mechanism, and comprising cams arranged in two complementary sets, a pair of levers respectively controlled by said sets of cams, a rotary shaft for actuating the feed, a ratchet wheel fast on said shaft, a pair of geared sectors pivoted on said shaft and provided with coöperative abutments for limiting the movement of one toward the other, a pawl carried by one of said sectors and engaging said ratchet wheel, a pair of rock arms each provided with a geared sector in mesh with said sectors pivoted on the said shaft and controlled by said levers respectively, said cams being effective to move the sector carrying the pawl a determined distance and to move the other sector for bringing said abutments into engagement for positively limiting the feed movement.

112. The combination with a type-forming mechanism having a set of type-dies for forming characters of different widths, of selecting means controlling said respective dies, means for bringing each selected die to its working position, cams arranged in two complementary sets, each having a predetermined feed dimension corresponding in feed value with the width of one or more dies and each controlled in its operation by the positioning of a corresponding type-die, a rotary shaft for actuating the feed, a ratchet wheel fast on said shaft, a pair of geared sectors pivoted on said shaft and provided with coöperative abutments for limiting the movement of one toward the other, a pawl carried by one of said sectors and engaging said ratchet wheel, a pair of rock arms each provided with a geared sector and respectively in mesh with said sectors pivoted on the said shaft and respectively controlled by said sets of cams, said cams being effective to move the sector carrying the pawl a determined distance, and to move the other sector for bringing said abutments into engagement for positively limiting the feed movement.

113. The combination with a type-forming mechanism having a set of type-dies for forming characters of different widths the width of each die being a multiple of a given unit, of selecting means controlling said respective dies, means for bringing each selected die to its working position, and two sets of devices each embodying a plurality of feed-indicators for controlling feed movements which are multiples of a given unit,

and each feed-indicator having a predetermined feed dimension corresponding in feed value with the width of one or more dies and each controlled in its operation by the positioning of a corresponding type-die, said sets being complementary one of the other and one of said sets being effective to impart feed movements of determined value and the other to positively stop said feed movement for preventing overthrow. 75

114. The combination with a typebar blank carrier, of a plurality of series of normally inoperative type forming tools, means for conveying the same periodically to the working point in respect to said typebar blank carrier, and key controlled means for selecting tools from a number of said series.

115. The combination with a blank carrier, of a plurality of series of coöperative character forming members, a series of selectors each effective for selecting a working complement of members embracing a member from each of a number of said series and effective when sequentially brought into working engagement with a blank for forming 90 a character, and means for bringing a selected complement of said members in sequence into working engagement with a blank in said carrier. 85

116. The combination with a series of selective dies, of a blank carrier, a plurality of series of coöperative members, a series of selectors each effective for selecting a die and a working complement of said members, a complement of members embracing a member from each of a number of said series and coöperative with a die when sequentially brought into working engagement with a blank for forming a character, and means for bringing a selected complement of said members and a selected die in sequence into working engagement with a blank in said carrier. 100

117. The combination with a blank carrier, of a plurality of series of coöperative character forming members, selectors effective for selecting a working complement of members embracing a member from each of a number of said series and effective for forming a character when brought into working engagement with a blank in an arbitrary permutation of sequence, and means for bringing a selected complement of said members sequentially into working engagement with a blank in said carrier. 110

118. The combination with a series of selective dies, of a blank carrier, a plurality, less in number than the number of dies, of series of coöperative members, a series of selectors each effective for selecting a die and a working complement of said members, a complement of members embracing a member from each of a number of said series and coöperative with a die when sequentially brought into working engagement with a blank for forming a character, and means for 120 125 130

- bringing a selected complement of said members and a selected die in an arbitrary permutation of sequence into working engagement with a blank in said carrier.
- 5 119. The combination with a blank carrier, of a plurality of series of coöperative character forming members, a series of latches each effective for selecting an arbitrary working complement of members embracing a member from each of a number of said series and effective for forming a character when brought into working engagement with a blank in an arbitrary permutation of sequence, means for selectively actuating 10 said latches, and means for bringing a selected complement of said members sequentially into working engagement with a blank in said carrier.
- 15
120. The combination with a turret, of a plurality of rotary carriers on said turret, a blank carrier, a series of character forming devices mounted on each of said carriers, a working complement of said members embracing a member from each of a number of said series and coöperative when sequentially 20 brought into working engagement with a blank for forming a character, and means for selectively placing a complement of said members in position to be brought into working engagement with a blank in said blank 25 carrier upon the rotation of the turret.
